INTERMEDIATES FOR 18-O-ALKYL-RESERPIC ACID ESTERS AND RELATED COMPOUNDS

Michael Mullen Robison, Berkeley Heights, and Robert Armistead Lucas, Mendham, N.J., assignors to Ciba Corporation, a corporation of Delaware
No Drawing. Filed June 20, 1960, Ser. No. 37,097
18 Claims. (Cl. 260—240)

The present invention concerns 3-epi-allo-yohimbane compounds having the nucleus of the formula:

More particularly, it relates to 18-etherified hydroxy-17-lower alkoxy-3-epi-allo-yohimbane 16-carboxylic acid esters, salts of such compounds, N-oxides thereof and salts of such N-oxides. Apart from the already mentioned groups, the compounds may contain additional substituents; such substituents are, for example, aliphatic hydrocarbon, such as lower alkyl and the like, etherified hydroxyl, such as lower alkoxy, cycloalkyloxy, cycloalkyl-lower alkoxy, carbocyclic aryloxy, carbocyclic aryl-lower alkoxy, lower alkyleneoxy and the like, etherified hydroxyl, such as lower alkoxy-carbonyloxy, lower alkanoyloxy, halogeno and the like, etherified mercapto, such as lower alkylmercapto and the like, nitro, amino, such as N,N-disubstituted amino and the like, halogeno-lower alkyl or any other suitable substituent. These substituents are preferably attached to positions of the aromatic nucleus, i.e. ring A, of the molecule, which are available for substitution, i.e. positions 9, 10, 11 and/or 12; the substituents, particularly aliphatic hydrocarbon radicals, may also be attached to positions of other nuclei, particularly of the heterocyclic nucleus C.

More especially, the invention is directed to compounds of the formula:

in which R₁ represents lower alkyl or substituted lower alkyl, such as, for example, etherified hydroxy-lower alkyl, e.g. lower alkoxy-lower alkyl and the like, as well as tertiary amino-lower alkyl, e.g. N,N-di-lower alkyl-amino-lower alkyl and the like, R₂ stands for lower alkyl, R₃ represents aliphatic hydrocarbon, particularly lower alkyl and the like, or substituted aliphatic hydrocarbon, such as, for example, etherified hydroxy-lower alkyl, e.g. lower alkoxy-lower alkyl and the like, tertiary amino-lower alkyl, e.g. N,N-di-lower alkyl-amino and the like,

each of the radicals R₄ and R₅ stands for hydrogen, lower aliphatic hydrocarbon, especially lower alkyl, etherified hydroxyl, particularly lower alkoxy, halogeno, or etherified mercapto, particularly lower alkyl-mercaptop, as well as other etherified hydroxyl groups, such as cycloalkyloxy, cycloalkyl-lower alkoxy, carbocyclic aryloxy, carbocyclic aryl-lower alkoxy and the like, etherified hydroxyl, e.g. lower alkoxy-carbonyloxy, lower alkanoyloxy and the like, nitro, amino, e.g. N,N-di-substituted amino and the like, or halogeno-lower alkyl, or, when attached to adjacent positions and taken together, for lower alkyleneoxy, and R₆, attached to one of the positions 5 and 6, stands for hydrogen or lower alkyl, salts thereof, N-oxides thereof or salts of such N-oxides, as well as process for the preparation of such compounds.

The radical of the alcohol portion of the ester grouping attached to the 16-position of the molecule, which is also represented by the group R₁ in the above formula, stands primarily for a lower alkyl group containing from one to seven, preferably from one to four, carbon atoms; such groups are, for example, methyl, ethyl, n-propyl, isopropyl, n-butyl, isobutyl, as well as n-pentyl, isopentyl, n-hexyl, n-heptyl, and the like.

The esterifying group of the ester grouping attached to the 16-position of the molecule, represented, for example, by the radical R₁ in the formula, may also stand for a substituted lower alkyl radical, such as, for example, etherified hydroxy-lower alkyl, as well as tertiary amino-lower alkyl and the like. An etherified hydroxy-lower alkyl radical represents primarily lower alkoxy-lower alkyl, in which lower alkoxy contains from one to four carbon atoms and represents, for example, methoxy, ethoxy, n-propoxy, isopropoxy, n-butyloxy and the like. The amino group of a tertiary amino-lower alkyl radical is primarily an N,N-di-lower alkyl-amino group, in which lower alkyl contains from one to four carbon atoms, e.g. N,N-dimethylamino, N-ethyl-N-methylamino, N,N-diethylamino, N,N-di-n-propylamino, N,N-di-isopropylamino and the like, as well as a 1-N,N-lower alkylene-imino group, in which lower alkylene contains from four to six ring carbon atoms, e.g. 1-pyrrolidino, 1-piperidino, 1-N,N-hexamethyleneimino and the like, a 1-N,N-lower oxa-alkylene-imino-group, in which lower oxa-alkylene contains preferably four ring carbon atoms, e.g. 1-morpholino and the like, or a 1-N,N-lower aza-alkyleneimino group, in which lower aza-alkylene contains from four to six ring carbon atoms, particularly 4-lower alkyl-1-piperazino, e.g. 4-methyl-1-piperazino and the like.

50 The lower alkyl portion in a substituted lower alkyl radical, represented, for example, by R₁, such as in an etherified hydroxy-lower alkyl group and the like, may be a lower alkylene radical containing from two to seven carbon atoms, which separates the substituent, such as the etherified hydroxyl group and the like, from the carbon atom of the carboxy group by at least two carbon atoms. Preferably, such lower alkylene radical contains from two to three carbon atoms and separates the substituent, such as the etherified hydroxyl group and the like, from the carboxy group by the same number of carbon atoms. The alkylene radicals are primarily 1,2-ethylene, 1-methyl-1,2-ethylene, 2-methyl-1,2-ethylene or 1,3-propylene; other lower alkylene radicals may be, for example, 1,4-butylene, 1-methyl-1,3-propylene and the like.

55 The lower alkyl portion of the lower alkoxy group attached to the 17-position of the molecule and represented, for example, by R₂ in the previously given formula, contains from one to four carbon atoms, and stands for ethyl, n-propyl, isopropyl, n-butyl, isobutyl and the like, but represents, above all, methyl.

Generally, the etherified hydroxyl group attached to

the 18-position of the yohimbane molecule and represented, for example, by the grouping R_3-O- in the previously given formula, is etherified by an aliphatic hydrocarbon radical. Such radical representing, for example, the group R_3 , stands for lower alkyl, containing from one to seven, preferably from one to four, carbon atoms, such as, for example, methyl, ethyl, n-propyl, isopropyl, n-butyl, isobutyl, n-pentyl, isopentyl, neopentyl, n-hexyl, n-heptyl and the like.

The etherifying group, as represented, for example, by the radical R_3 , may also be a substituted aliphatic hydrocarbon radical, such as, for example, an etherified hydroxy-lower alkyl radical, such as lower alkoxy-lower alkyl, in which lower alkoxy contains from one to four carbon atoms and stands, for example, for methoxy, ethoxy, n-propoxy, n-butyloxy and the like, or a tertiary amino-lower alkyl radical, in which tertiary amino represents, for example, N,N-di-lower alkyl-amino, e.g. N,N-dimethylamino, N-ethyl-N-methyl-amino, N,N-diethyl-amino, N,N-di-n-propylamino, N,N-di-isopropylamino, N,N-dibutylamino and the like, N,N-lower alkylene-imino, in which alkylene contains, primarily, from four to six carbon atoms, e.g. 1-pyrrolidino, 1-piperidino, 1-N,N-hexamethyleneimino and the like, 1-N,N-lower-oxa-alkylene-imino, in which alkylene contains, primarily, four carbon atoms, e.g. 1-morpholino and the like, 1-N,N-lower-aza-alkylene-imino, in which alkylene contains from four to six ring carbon atoms, particularly 4-lower alkyl-1-piperazino, e.g. 4-methyl-1-piperazino and the like. Preferably, a functional group is separated from the oxygen atom, to which the radical R_3 is attached, by from two to seven, advantageously by from two to three, carbon atoms. Substituted aliphatic hydrocarbon radicals, particularly those representing R_3 , are, therefore, 2-lower alkoxy-ethyl, e.g. 2-methoxyethyl, 2-ethoxyethyl and the like, 2-lower alkoxy-propyl, e.g. 2-methoxy-propyl, 2-ethoxy-propyl and the like, 3-lower alkoxy-propyl, e.g. 3-methoxy-propyl, 3-ethoxy-propyl and the like, 2-N,N-di-lower alkyl-amino-ethyl, e.g. 2-N,N-dimethylaminoethyl, 2-N,N-diethylaminoethyl and the like, 2-N,N-di-lower alkyl-amino-propyl, e.g. 2-N,N-dimethylaminopropyl, 2-N,N-diethylaminopropyl and the like, 3-N,N-di-lower alkyl-amino-propyl, e.g. 3-N,N-dimethylaminopropyl, 3-N,N-diethylaminopropyl and the like, 2-N,N-lower alkylene-imino-ethyl, e.g. 2-(1-pyrrolidino)-ethyl, 2-(1-piperidino)-ethyl and the like, 3-N,N-lower alkylene-imino-propyl, e.g. 3-(1-pyrrolidino)-propyl, 3-(1-piperidino)-propyl and the like, 2-(4-lower alkyl-1-piperazino)-ethyl, e.g. 2-(4-methyl-1-piperazino)-ethyl, 2-(4-ethyl-1-piperazino)-ethyl and the like, or 3-(4-lower alkyl-1-piperazino)-propyl, e.g. 3-(4-methyl-1-piperazino)-propyl, 3-(4-ethyl-1-piperazino)-propyl and the like.

Other etherified hydroxyl groups contain as etherifying groups, represented, for example, by the radical R_3 in the above-given formula, other aliphatic radicals, such as, for example, lower alkenyl, such as lower allylic alkenyl, containing preferably from three to five carbon atoms, e.g. allyl, 2-methyl-allyl, 2-but enyl, 3-methyl-2-but enyl, 2-pentenyl and the like, cycloalkyl containing from three to eight, preferably from five to six, ring carbon atoms, e.g. cyclopentyl or cyclohexyl, as well as cyclopropyl, cycloheptyl, cyclo-octyl and the like, cycloalkenyl, containing preferably from five to six ring carbon atoms, e.g. 3-cyclopentenyl, 2-cyclohexenyl and the like, cycloalkyl-lower alkyl, in which cycloalkyl contains from three to eight, especially from five to six, ring carbon atoms, and lower alkyl contains from one to four carbon atoms, e.g. cyclopentylmethyl, 1-cyclopentyl-ethyl, 2-cyclopentylethyl, cyclohexylmethyl, 2-cyclohexyl-ethyl and the like, carbocyclic aryl-aliphatic hydrocarbon radicals, such as monocyclic carbocyclic aryl-lower alkyl, e.g. benzyl, diphenylmethyl, 1-phenylethyl, 2-phenylethyl and the like and analogous radicals, in which the carbocyclic aryl nucleus is substituted, for example, by lower alkyl, e.g. methyl, ethyl and the like,

lower alkoxy, e.g. methoxy, ethoxy and the like, lower alkenyloxy, e.g. allyloxy and the like, halogeno, e.g. chloro, bromo and the like, lower alkoxy-carbonyloxy, e.g. methoxy-carbonyloxy, ethoxy-carbonyloxy and the like, halogeno-lower alkyl, e.g. trifluoromethyl and the like, nitro, amino, such as N,N-di-lower alkyl-amino, e.g. N,N-dimethylamino and the like, or any other suitable substituent, or monocyclic carbocyclic aryl-lower alkenyl, e.g. 3-phenyl-allyl and the like and analogous radicals containing substituents, such as those previously mentioned to be attached to the carbocyclic aryl nucleus.

Additional substituted aliphatic hydrocarbon radicals are particularly lower alkyl radicals substituted by functional groups, such as, for example, by acyl, particularly lower alkanoyl, e.g. acetyl, propionyl and the like, or carbo-lower alkoxy, e.g. carbomethoxy carbethoxy and the like, etherified mercapto, such as lower alkyl-merc capo, e.g. methylmerc capo, ethylmerc capo and the like, halogeno, e.g. chloro, bromo and the like, or any other substituent suitable for being attached to an aliphatic hydrocarbon, particularly a lower alkyl, radical. These substituted aliphatic radicals are, therefore, primarily lower alkanoyl-lower alkyl, e.g. acetyl-methyl, propionyl-methyl and the like, carbo-lower alkoxy-lower alkyl, e.g. carbomethoxymethyl, carbethoxymethyl and the like, lower alkyl-merc capo, e.g. methylmerc capo, ethylmerc capo and the like, halogeno-lower alkyl, e.g. chloro-methyl and the like, as well as other analogous substituents.

Substituents attached to any of the positions available for substitution in ring A, particularly those representing the groups R_4 and R_5 (each of which may also stand for hydrogen) in the previously given formula, may be represented, for example, by lower aliphatic hydrocarbon, especially lower alkyl, containing preferably from one to four carbon atoms, e.g. methyl, ethyl, n-propyl, isopropyl, n-butyl and the like, or by functional groups, such as, for example, etherified hydroxyl, particularly lower alkoxy, containing preferably from one to four carbon atoms, e.g. methoxy, ethoxy, n-propoxy, isopropoxy, n-butyloxy, isobutyloxy and the like, as well as cycloalkyloxy, e.g. cyclopentyloxy, cyclohexyloxy and the like, cycloalkyl-lower alkoxy, e.g. cyclopentylmethoxy, 2-cyclopentyl-ethoxy, cyclohexylmethoxy and the like, carbocyclic aryloxy, such as monocyclic carbocyclic aryloxy, e.g. phenoxy and the like, carbocyclic aryl-lower alkoxy, such as monocyclic carbocyclic aryl-lower alkoxy, for example, phenyl-lower alkoxy, e.g. benzylxy, diphenylxy, 2-phenylethoxy and the like, etherified hydroxyl, particularly lower alkoxy-carbonyloxy, e.g. methoxy-carbonyloxy, ethoxy-carbonyloxy and the like, or lower alkanoyloxy, e.g. acetoxy, propionyloxy and the like, etherified mercapto, particularly lower alkyl-merc capo, containing preferably from one to four carbon atoms, e.g. methylmerc capo, ethylmerc capo and the like, nitro, amino, particularly N,N-disubstituted amino, such as N,N-di-lower alkyl-amino, e.g. N,N-dimethylamino, N-ethyl-N-methyl-amino, N,N-diethylamino and the like, halogeno, e.g. fluoro, chloro, bromo, iodo and the like, halogeno-lower alkyl, e.g. trifluoromethyl and the like, or any other suitable functional group. A substituent may also be attached to two adjacent positions of ring A and form an additional ring; for example, the radicals R_4 and R_5 in the formula, when taken together and substituting two neighboring positions, may also form a cyclic substituent. Such substituents may be represented, for example, by lower alkylene-dioxy, e.g. methylenedi oxy, or any other analogous grouping.

Substituents, which may be attached to other positions in the molecule, particularly to the positions available for substitution in ring C are particularly aliphatic hydrocarbon, such as lower alkyl radicals, containing preferably from one to four carbon atoms, particularly methyl, as well as ethyl, n-propyl, isopropyl and the like. The radical R_6 in the previously given formula, which stands

primarily for hydrogen, may, therefore, also stand for lower alkyl, particularly for methyl.

Salts of the compounds of this invention are primarily therapeutically acceptable acid addition salts, particularly those with inorganic acids, particularly with mineral acids, e.g. hydrochloric, hydrobromic, sulfuric, phosphoric acids and the like, as well as with organic acids, e.g. acetic, tartaric, methane sulfonic acid and the like.

Also included within the scope of the present invention are the N-oxides of the above-mentioned compounds, as well as the therapeutically acceptable acid addition salts of such N-oxides, for example, the addition salts with the above-mentioned inorganic, particularly mineral, and organic acids.

In view of the fact that several asymmetric carbon atoms are present in the compounds of this invention, the latter may be obtained in the form of a mixture of racemates, racemates or optically pure compounds.

The compounds of the present invention have sedative and tranquilizing effects on the central nervous system, as well as antihypertensive properties. In addition, qualitative differences can be observed within the group of the new compounds of this invention. For example, when compared with the ratio existing between antihypertensive and sedative effects in naturally occurring *Rauwolfia* alkaloids, such as, for example, reserpine, deserpidine, rescinnamine and the like, certain compounds of this invention have more predominant sedative effects with negligible antihypertensive activity, whereas in others, the latter may be more pronounced than the sedative and tranquilizing component.

Furthermore, it has also been found that contrary to the naturally occurring compounds, which show a slow onset of the pharmacological action and an often undesirably long lasting effect, the compounds of this invention react quickly and the activity is of definite duration, i.e. the recovery after treatment is more complete and easily controllable. It has also been found that the therapeutically acceptable salts, particularly those with mineral acids, e.g. hydrochloric acid and the like, are to a high degree water-soluble, and are, therefore, extremely useful in the preparation of aqueous solutions for injection and in aqueous oral preparations, e.g. elixirs and the like.

The compounds of the present invention can, therefore, be used as sedative and tranquilizing agents to relieve states of hyperactivity tension and agitation, as, for example, associated with mental disturbances and the like. Furthermore, they can be used as antihypertensive agents to relieve hypertensive conditions, such as, for example, benign or malignant hypertension, renal hypertension or hypertension associated with pregnancy, such as toxemia of pregnancy. They also can be used as intermediates for the formation of other useful compounds.

A preferred group of compounds having the above-given properties is represented by those of the formula:

in which each of the groups R₁' and R₃' represents lower alkyl, containing preferably from one to four carbon atoms.

atoms, especially methyl, as well as ethyl, n-propyl, isopropyl, n-butyl, isobutyl, secondary butyl and the like, and R₄' represents lower alkoxy containing from one to four carbon atoms, particularly methoxy, as well as ethoxy, n-propoxy, isopropoxy, n-butoxy and the like, whereby R₄' is preferably attached to the 10-position or the 11-position, the therapeutically acceptable acid addition salts, the N-oxides and the therapeutically acceptable acid addition salts of such N-oxides.

10 An outstanding member of this group of compounds, which has pronounced sedative and tranquilizing effect of fast onset and easily controllable duration, accompanied by negligible antihypertensive properties, is the methyl 18-O-methyl-reserpate of the formula:

30 and the therapeutically acceptable mineral acid addition salts thereof, such as the hydrochloride and the like.

Other specific compounds of the previously mentioned group are, for example, methyl 18-O-ethyl-reserpate, methyl 18-O-n-propyl-reserpate, methyl 18-O-isopropyl-reserpate, methyl 18-O-n-butyl-reserpate, methyl 18-O-isobutyl-reserpate, ethyl 18-O-methyl-reserpate, ethyl 18-O-ethyl-reserpate, ethyl 18-O-n-propyl-reserpate, ethyl 18-O-n-butyl-reserpate, n-propyl 18-O-methyl-reserpate, n-propyl 18-O-ethyl-reserpate, isopropyl 18-O-methyl-reserpate, isopropyl 18-O-n-propyl-reserpate, n-butyl 18-O-methyl-reserpate, n-butyl 18-O-ethyl-reserpate, isobutyl 18-O-methyl-reserpate, n-pentyl 18-O-methyl-reserpate, n-hexyl 18-O-methyl-reserpate and the like.

45 Other compounds of the aforementioned formula are, for example, the lower alkyl 18-O-lower alkyl-9-methoxy-deserpipidate, e.g. methyl 9-methoxy-18-O-methyl-deserpipidate, methyl 18-O-ethyl-9-methoxy-deserpipidate, methyl 9-methoxy-18-O-n-propyl-deserpipidate, ethyl 9-methoxy-18-O-methyl-deserpipidate and the like, lower alkyl 18-O-lower alkyl-10-methoxy-deserpipidate, e.g. methyl 10-methoxy-18-O-methyl-deserpipidate, methyl 18-O-ethyl-10-methoxy-deserpipidate, methyl 10-methoxy-18-O-n-propyl-deserpipidate, ethyl 10-methoxy-18-O-methyl-deserpipidate, n-propyl 10-methoxy-18-O-methyl-deserpipidate, isopropyl 10-methoxy-18-O-methyl-deserpipidate and the like, lower alkyl 11-ethoxy-18-O-lower alkyl-deserpipidate, e.g. methyl 11-ethoxy-18-O-methyl-deserpipidate, methyl 11-ethoxy-18-O-ethyl-deserpipidate and the like, lower alkyl 18-O-lower alkyl-11-n-propoxy-deserpipidate, e.g. methyl 18-O-methyl-11-n-propoxy-deserpipidate, methyl 18-O-ethyl-11-n-propoxy-deserpipidate and the like, lower alkyl 11-isopropoxy-18-O-lower alkyl-deserpipidate, e.g. methyl 11-isopropoxy-18-O-methyl-deserpipidate, ethyl 11-isopropoxy-18-O-methyl-deserpipidate and the like, lower alkyl 11-n-butyloxy-18-O-lower alkyl-deserpipidate, e.g. methyl 11-n-butyloxy-18-O-methyl-deserpipidate, methyl 11-n-butyloxy-18-O-ethyl-deserpipidate and the like, lower alkyl 18-O-lower alkyl-12-methoxy-deserpipidates, e.g. methyl 12-methoxy-18-O-methyl-deserpipidate, ethyl 12-methoxy-18-O-methyl-deserpipidate and the like.

An additional preferred group of compounds are the lower alkyl 18-O-lower alkyl-deserpipidates, in which lower alkyl contains preferably from one to four carbon atoms, and is represented primarily by methyl, as well as ethyl,

n-propyl, isopropyl, n-butyl, isobutyl and the like, the therapeutically acceptable acid addition salts thereof, the N-oxides thereof and the therapeutically acceptable acid addition salts of such N-oxides. Specific members of this group are, for example, methyl 18-O-methyl-deserpipidate, methyl 18-O-ethyl-deserpipidate, methyl 18-O-n-propyl-deserpipidate, methyl 18-O-isopropyl-deserpipidate, methyl 18-O-n-butyl-deserpipidate, methyl 18-O-secondary butyl-deserpipidate, ethyl 18-O-methyl-deserpipidate, ethyl 18-O-ethyl-deserpipidate, ethyl 18-O-n-propyl-deserpipidate, n-propyl 18-O-methyl-deserpipidate, n-propyl 18-O-ethyl-deserpipidate, isopropyl 18-O-n-butyl-deserpipidate, n-butyl 18-O-methyl-deserpipidate, secondary butyl 18-O-methyl-deserpipidate, n-pentyl 18-O-methyl-deserpipidate and the like.

Other compounds having the useful pharmacological properties previously mentioned, are, for example, lower alkyl 18-O-lower alkyl-5-methyl-reserpates, e.g. methyl 5-methyl-18-O-methyl-reserpate, methyl 18-O-ethyl-5-methyl-reserpate, ethyl 5-methyl-18-O-methyl-reserpate and the like, lower alkyl 18-O-lower alkyl-6-methyl-reserpates, e.g. methyl 6-methyl-18-O-methyl-reserpate, methyl 18-O-n-butyl-6-methyl-reserpate, ethyl 6-methyl-18-O-methyl-reserpate and the like, lower alkyl 18-O-lower alkyl-6-methyl-deserpipidate, e.g. methyl 6-methyl-18-O-methyl-deserpipidate, methyl 6-methyl-18-O-n-propyl-deserpipidate, ethyl 6-methyl-18-O-methyl-deserpipidate and the like, lower alkyl 18-O-lower alkyl-9-methyl-deserpipidate, e.g. methyl 9-methyl-18-O-ethyl-deserpipidate, methyl 9-methyl-18-O-n-propyl-deserpipidate and the like, lower alkyl 18-O-lower alkyl-11-methyl-deserpipidate, e.g. methyl 11-methyl-18-O-methyl-deserpipidate, ethyl 11-methyl-18-O-n-butyl-deserpipidate and the like, lower alkyl 18-O-lower alkyl-10-methoxy-reserpate, e.g. methyl 10-methoxy-18-O-methyl-reserpate, methyl 18-O-ethyl-10-methoxy-reserpate, ethyl 10-methoxy-18-O-n-propyl-reserpate and the like, lower alkyl 18-O-lower alkyl-10,11-lower alkylenedioxy-deserpipidate, e.g. methyl 18-O-methyl-10,11-methylenedioxy-deserpipidate, ethyl 18-O-methyl-10,11-methylenedioxy-deserpipidate and the like, lower alkyl 10-benzyloxy-18-O-lower alkyl-deserpipidate, e.g. methyl 10-benzyloxy-18-O-methyl-deserpipidate, methyl 10-benzyloxy-18-O-ethyl-deserpipidate, ethyl 10-benzyloxy-18-O-methyl-deserpipidate and the like, lower alkyl 11-benzyloxy-18-O-lower alkyl-deserpipidate, e.g. methyl 11-benzyloxy-18-O-methyl-deserpipidate, methyl 11-benzyloxy-18-O-ethyl-deserpipidate, ethyl 11-benzyloxy-18-O-methyl-deserpipidate and the like, lower alkyl 18-O-lower alkyl-11-methylmercapto-deserpipidate, e.g. methyl 18-O-methyl-11-methylmercapto-deserpipidate, methyl 18-O-ethyl-11-methylmercapto-deserpipidate, ethyl 18-O-methyl-11-methylmercapto-deserpipidate and the like, lower alkyl 11-ethyl-mercapto-18-O-lower alkyl-deserpipidate, e.g. methyl 11-ethylmercapto-18-O-methyl-deserpipidate, ethyl 18-O-ethyl-11-ethylmercapto-deserpipidate, n-propyl 11-ethylmercapto-18-O-methyl-deserpipidate and the like, lower alkyl 10-chloro-18-O-lower alkyl-deserpipidate, e.g. methyl 10-chloro-18-O-methyl-deserpipidate, methyl 10-chloro-18-O-ethyl-deserpipidate, ethyl 10-chloro-18-O-n-butyl-deserpipidate and the like, lower alkyl 10-bromo-18-O-lower alkyl-reserpate, e.g. methyl 10-bromo-18-O-methyl-reserpate, methyl 10-bromo-18-O-ethyl-reserpate, ethyl 10-bromo-18-O-ethyl-reserpate and the like, lower alkyl 17 α -desmethoxy-17 α -ethoxy-18-O-lower alkyl-reserpate, e.g. methyl 17 α -desmethoxy-17 α -ethoxy-18-O-methyl-reserpate, methyl 17 α -desmethoxy-17 α -ethoxy-18-O-ethyl-reserpate and the like, lower alkyl 17 α -desmethoxy-18-O-lower alkyl-17 α -n-propyloxy-reserpate, e.g. methyl 17 α -desmethoxy-18-O-methyl-17 α -n-propyloxy-reserpate, ethyl 17 α -desmethoxy-18-O-methyl-17 α -n-propyloxy-reserpate and the like, lower alkyl 17 α -desmethoxy-17 α -isopropoxy-18-O-lower alkyl-reserpate, e.g. methyl 17 α -desmethoxy-17 α -isopropoxy-18-O-methyl-reserpate, methyl 17 α -desmethoxy-18-O-ethyl-17 α -isopropoxy-reserpate and the like, lower alkyl 17 α -desmethoxy-

17 α -ethoxy-18-O-lower alkyl-deserpipidate, e.g. methyl 17 α -desmethoxy-17 α -ethoxy-18-O-methyl-deserpipidate, methyl 17 α -desmethoxy-17 α -ethoxy-18-O-ethyl-deserpipidate, ethyl 17 α -desmethoxy-17 α -ethoxy-18-O-ethyl-deserpipidate and the like, or analogous compounds.

Also included in the scope of the invention are, for example, lower alkoxy-lower alkyl 18-O-lower alkyl-reserpates and lower alkoxy-lower alkyl 18-O-lower alkyl-deserpipidates, in which lower alkyl of the lower alkoxy-lower alkyl portion represents a lower alkylene radical which contains from two to three carbon atoms and separates the lower alkoxy group from the carbon atom of the carboxyl group by the same number of carbon atoms, and lower alkoxy has from one to four carbon atoms, whereas the lower alkyl group attached to the oxygen atom of the 18-position contains from one to four carbon atoms; lower alkoxy-lower alkyl represents, for example, 2-methoxyethyl, 2-ethoxyethyl, 2-methoxypropyl, 3-methoxyethyl and the like, and lower alkyl may stand for methyl, ethyl, n-propyl, isopropyl, n-butyl or isobutyl and the like. Specific compounds of this group are, for example, 2-methoxyethyl 18-O-methyl-reserpate, 2-methoxyethyl 18-O-ethyl-reserpate, 2-ethoxyethyl 18-O-methyl-reserpate, 2-ethoxyethyl 18-O-n-propyl-reserpate, 2-methoxypropyl 18-O-methyl-reserpate, 3-methoxypropyl 18-O-methyl-reserpate, 2-methoxyethyl 18-O-methyl-deserpipidate, 2-methoxyethyl 18-O-ethyl-deserpipidate, 2-ethoxyethyl 18-O-methyl-deserpipidate and the like.

An additional group of compounds is represented by the N,N-di-lower alkyl-amino-lower alkyl 18-O-lower alkyl-reserpates and N,N-di-lower alkyl-amino-lower alkyl 18-O-lower alkyl-deserpipidates, in which N,N-di-lower alkyl-amino stands for N,N-dimethylamino, N-ethyl-N-methylamino, N,N-diethylamino and the like, and in which lower alkyl, separating the N,N-di-lower alkyl-amino group, represents a lower alkylene radical containing from two to three carbon atoms and separating the N,N-di-lower alkyl-amino group from the carbon atom of the carboxyl group by from two to three carbon atoms; N,N-di-lower alkyl amino-lower alkyl represents, for example, 2-N,N-dimethylaminoethyl, 2-N,N-diethylaminoethyl, 2-N,N-dimethylaminopropyl, 3-N,N-dimethylaminopropyl and the like. Specific compounds of this group are, for example, 2-N,N-dimethylaminoethyl 18-O-methyl-reserpate, 2-N,N-dimethylaminoethyl 18-O-ethyl-reserpate, 2-N,N-diethylaminoethyl 18-O-methyl-reserpate, 3-N,N-dimethylaminopropyl 18-O-methyl-reserpate, 2-N,N-dimethylaminoethyl 18-O-methyl-deserpipidate, 2-N,N-dimethylaminoethyl 18-O-ethyl-deserpipidate, 2-N,N-dimethylaminopropyl 18-O-methyl-deserpipidate and the like.

The compounds of this invention may be used as medicaments in the form of pharmaceutical preparations, which contain the new compounds or derivatives thereof, such as therapeutically acceptable acid addition salts thereof, N-oxides thereof or therapeutically acceptable acid addition salts of N-oxides thereof in admixture with a pharmaceutical organic or inorganic, solid or liquid carrier suitable for enteral or parenteral administration. For making up the preparations there can be employed inert substances which are compatible with the new compounds, such as water, gelatine, lactose, starches, stearic acid, magnesium stearate, stearyl alcohol, talc, vegetable oils, benzyl alcohols, gums, waxes, propylene glycol, poly-alkylene glycols or any other known inert carrier used in medicaments. The pharmaceutical preparation may be in solid form, for example, as tablets, capsules, dragees and the like, or in liquid form, for example, as solutions, suspension, emulsions and the like. If desired, they may contain additional substances such as preserving, stabilizing, wetting, emulsifying agents and the like, salts for varying the osmotic pressure, buffers or any other auxiliary substances. They may also contain, in combination, other therapeutically useful substances.

Compounds of this invention can be formed by etherify-

ing in an 18-hydroxy-17-lower alkoxy-3-epi-allo-yohimbane 16-carboxylic acid ester, particularly in a compound of the formula:

in which R₁, R₂, R₄, R₅ and R₆ have the previously given meaning, a salt thereof, an N-oxide thereof or a salt of an N-oxide thereof, the free hydroxyl group attached to the 18-position by treatment with a diazo-compound in the presence of a strong inorganic Lewis acid, and, if desired, converting a resulting salt into the free base, and/or, if desired, converting a resulting compound into a salt, an N-oxide or a salt of an N-oxide thereof, and/or, if desired, converting a resulting mixture of isomers into the single isomers.

Salts of the starting materials or of an N-oxide thereof, are addition salts with acids, primarily those with inorganic, such as mineral, acids, e.g. hydrochloric, hydrobromic, sulfuric, phosphoric acid and the like. Acid addition salts may also be those with the strong inorganic Lewis acid catalyzing the etherification reaction, e.g. fluoroboric acid and the like; these salts may be formed during the reaction.

The starting materials, the salts, the N-oxides or the salts of N-oxides thereof are reacted with the aliphatic diazo-hydrocarbon, for example, a lower diazo-alkane, particularly diazomethane and the like, as well as with a substituted aliphatic diazo-hydrocarbon, such as an etherified hydroxy-lower diazo-alkane, particularly a lower alkoxy-lower diazo-alkane, a tertiary amino-lower diazo-alkane, particularly an N,N-di-lower alkyl-amino-lower diazo-alkane and the like, or any other suitable reagent, in the presence of a strong inorganic Lewis acid. Fluoroboric acid, which may be employed in the form of a concentrated aqueous solution (for example, an about 12 N to an about 16 N aqueous solution), represents the preferred reagent. Other Lewis acid reagents may be, for example, perchloric acid (preferably in anhydrous form) and the like. Due to the salt-forming properties of the free starting material, the Lewis acid, catalyzing the etherification of the 18-hydroxyl group, is used in excess of one mol, whenever the free base is present; an about one to an about two hundred, preferably an about ten to an about fifty, percent excess appears to be sufficient to promote the etherification reaction.

The reaction is carried out in the presence of solvents, which are inert towards the starting materials and the reaction reagents; such solvents are, for example, halogenated lower aliphatic hydrocarbons, e.g. methylene chloride, chloroform, ethylene chloride, trichloroethane, tetrachloroethane and the like, ethers, e.g. diethylether, tetrahydrofuran and the like, lower alkyl lower alkanoates, e.g. ethyl acetate and the like, acetonitrile or any other useful solvents, as well as mixtures of such solvents. A solution of the diazo reagent in an inert solvent such as an ether, e.g. diethylether and the like, or a halogenated hydrocarbon, e.g. methylene chloride and the like, or a mixture of solvents, may be added to the mixture of the starting material and the Lewis acid, preferably kept in solution. The diazo compound may also be distilled out

of its solution into the solution of the mixture of the starting material and the Lewis acid. Furthermore, the latter mixture may also be given to a solution of the diazo reagent.

5 The reaction may be carried out at room temperature; however, cooling of the reaction mixture to below room temperature, for example, to from about 10° to about -20°, especially to from about 0° to about -15°, may be advantageous. If necessary, the reaction may be carried out in the atmosphere of an inert gas, e.g. nitrogen.

10 An excess of the diazo reagent present at the end of the reaction may be destroyed, for example, by adding an acid, preferably an easily esterifiable carboxylic acid, e.g. acetic, benzoic acid and the like.

15 The desired product may be isolated and separated from any by-products according to standard procedures, e.g. extraction, adsorption and elution, crystallization, etc. and purified, for example, by recrystallization, if necessary, after treatment of a solution thereof with an adsorbent, e.g. aluminum oxide, charcoal, diatomaceous earth and the like.

20 The above-described procedure may be illustrated by the treatment of lower alkyl reserpate, particularly of methyl reserpate, with a lower diazo-alkane, such as diazomethane, in the presence of a strong Lewis acid, such as fluoroboric acid and the like, to form the desired lower alkyl 18-O-lower alkyl-reserpate (particularly the desired methyl 18-O-methyl-reserpate, which, if desired, may be converted into an acid addition salt, particularly a mineral acid, e.g. hydrochloric acid and the like, addition salt thereof).

25 The starting materials are known or, if new, may be prepared according to procedures used for known analogs. Thus, 18-hydroxy-17-lower alkoxy-3-epi-allo-yohimbane

30 35 16-carboxylic acids, such as, for example, compounds of the formula:

40 45 50 in which R₂, R₄, R₅ and R₆ have the previously given meaning, salts thereof, N-oxides thereof or salts of N-oxides thereof, may be esterified, for example, by treat-

55 ment with a lower diazo-alkane, or a substituted lower diazo-alkane, such as an etherified hydroxy-lower diazo-alkane, a tertiary amino-lower diazo-alkane and the like. For example, to a solution of the diazo reagent in an inert solvent, such as an ether, particularly diethylether,

60 may be added an acid of the above formula, a salt, an N-oxide or a salt of an N-oxide thereof, which is preferably kept in a suspension or a solution, for example, of a lower alkanol, e.g. methanol, ethanol and the like, a halogenated lower aliphatic hydrocarbon, e.g. chloroform,

65 methylene chloride and the like, or any other suitable, inert solvent. Or, the diazo compound may be distilled out of a solution, such as a diethylether solution, into the suspension or solution of the free acid used as the starting material. An excess of the diazo reagent present

70 in the reaction mixture may be destroyed, for example, by adding an additional carboxylic acid, e.g. acetic, benzoic acid and the like. The esterification may be carried out under cooling or at room temperature, and, if desired, under the atmosphere of an inert gas, e.g. nitrogen.

75 The starting materials may also be prepared by sub-

jecting (16→18)-lactones of 18-hydroxy-17-lower alkoxy-3-epi-allo-yohimbane 16-carboxylic acids, such as, for example, compounds of the formula:

a salt, an N-oxide or a salt of an N-oxide thereof, to alcoholysis with lower alkanols or substituted lower alkanols, such as etherified hydroxy-lower alkanols, tertiary amino-lower alkanols and the like, in the presence of an alcoholysis catalyst. The alcoholyzing reaction may be carried out, for example, by treating the lactone compound used as the starting material with a lower alkanol, or a substituted lower alkanol, such as an etherified hydroxy-lower alkanol, a tertiary amino-lower alkanol and the like, in the presence of an alcoholysis catalyst, for example, an alkali metal, e.g. sodium, potassium and the like, compound of the alcoholysis alcohol, or any other suitable catalyst, e.g. potassium cyanide, benzyl trimethyl ammonium hydroxide and the like. Although this reaction may proceed under cooling or at room temperature, the mixture is advantageously heated, if necessary, in the atmosphere of an inert gas, e.g. nitrogen.

N-oxides of the starting material may be prepared according to known N-oxidation methods; for example, a solution of the starting material in an inert solvent may be treated with a per-acid, such as, for example, peracetic, perbenzoic, mono-perphthalic, p-toluene persulfonic acid and the like, with hydrogen peroxide or with ozone and the like.

Salts or salts of N-oxides of the above-mentioned starting material may be prepared by treating the latter or an N-oxide thereof with an acid, particularly an inorganic acid, such as a mineral acid, e.g. hydrochloric, sulfuric, phosphoric acid and the like, preferably in the presence of a suitable solvent.

A modification of the above procedure, which yields 18-etherified hydroxy-17-lower alkoxy-3-epi-allo-yohimbane 16-carboxylic acid esters, in which the radical etherifying the 18-hydroxyl group and the group esterifying the 16-carboxyl group are identical, more particularly the compounds of the formula:

in which R1, R2, R3, R4, R5 and R6 have the previously given meaning, with the proviso that the radical R3 has the same meaning as the radical R1, salts, N-oxides or salts of N-oxides thereof, comprises reacting an 18-hy-

droxy-17-lower alkoxy-3-epi-allo-yohimbane 16-carboxylic acid, particularly a compound of the formula:

- 15 in which R2, R4, R5 and R6 have the above-given meaning, a salt, an N-oxide or a salt of an N-oxide thereof, with a lower diazo-alkane or with a substituted lower diazo-alkane, such as an etherified hydroxy-lower diazo-alkane, a tertiary amino-lower diazo-alkane and the like, in the presence of a strong Lewis acid and isolating the desired compound, and, if desired, carrying out the optional steps.

This reaction may be carried out according to the previously given method and is catalyzed by the necessary amount of a strong Lewis acid. It may also be carried out in such manner that first the reactive carboxyl group in the 16-position is esterified. This may be done by adding part (one mol or an excess) of the diazo-reagent to the free acid compound, using appropriate solvents, and, after the addition of the Lewis acid to catalyze the etherification, giving to the reaction mixture the additional amount (one mol or an excess) of the diazo-reagent.

The above reaction may be illustrated by the treatment of reserpic acid with an excess of diazomethane in the presence of a strong Lewis acid, such as fluoboric acid and the like, and isolation of the desired methyl 18-O-methyl-reserpate.

A further method for preparing the compounds of this invention comprises esterifying in 18-etherified hydroxy-17-lower alkoxy-3-epi-allo-yohimbane 16-carboxylic acid compounds, particularly in compounds of the formula:

- 45 in which R2, R3, R4, R5 and R6 have the above-given meaning, salts, N-oxides or salts of N-oxides thereof, the free carboxyl group attached to the 16-position, and, if desired, carrying out the optional steps.

The carboxyl group may be esterified according to known methods; for example, the starting material, preferably a solution thereof, may be treated with a diazo-reagent, such as, for example, an aliphatic diazo-hydrocarbon or a substituted aliphatic diazo-hydrocarbon. Such reagents are primarily lower diazo-alkanes, e.g. diazomethane, diazoethane, n-diazopropane, diazo-isopropane, n-diazobutane, diazo-isobutene and the like. Other reagents are, for example, etherified hydroxy-lower diazo-alkanes, such as lower alkoxy-lower diazo-alkanes, in which lower alkoxy is separated from the diazo group by at least two, preferably by from two to three carbon atoms, e.g. 2-methoxy-diazoethane, 2-ethoxy-diazoethane, 2-n-propoxy-diazoethane, 3-methoxydiazopropane and the like, tertiary amino-lower diazo-alkanes, particularly N,N-di-lower alkyl-amino-lower diazo-alkanes, in which the N,N-di-lower alkyl-amino group is separated from

the diazo group by at least two, preferably by from two to three, carbon atoms, e.g. 2-N,N-dimethylamino-diazoethane, 2-N,N-diethylamino-diazoethane, 3-N,N-dimethylamino-diazopropane and the like, as well as other tertiary amino-lower diazo-alkanes. These diazo reagents are advantageously used in solution with an inert diluent, such as, for example, an ether, e.g. diethylether and the like, or they may be distilled out of their solution into a solution of the starting material. An excess of the diazo-compound present after the completion of the reaction may be destroyed, for example, by adding an additional carboxylic acid, such as acetic, benzoic acid and the like.

The diazo-reagent may be given to the starting material or a solution thereof; suitable solvents are, for example, ethers, e.g. diethylether, tetrahydrofuran and the like, lower alkanols, e.g. methanol, ethanol and the like, halogenated hydrocarbons, e.g. chloroform, methylenechloride and the like, or any other appropriate solvents.

The above procedure may be illustrated by the treatment of 18-O-methyl-reserpic acid with diazomethane to form the desired methyl 18-O-methyl-deserpide.

The starting materials used in the above procedure, which are intended to be included within the scope of the invention, may be prepared, for example, by converting in an 18-etherified hydroxyl-17-lower alkoxy-3-epi-allo-yohimbane 16-carboxylic acid ester, particularly in compounds of the formula:

in which R₁, R₂, R₃, R₄, R₅ and R₆ have the above-given meaning, or a salt, an N-oxide or a salt of an N-oxide thereof, the esterified carboxyl group attached to the 16-position into a free carboxyl group, and, if desired, converting a resulting compound into a salt, an N-oxide or a salt of an N-oxide thereof.

Hydrolysis may be carried out according to known methods; for example, the esterified carboxyl group may be cleaved by treatment with an alkali metal hydroxide, e.g. sodium hydroxide, potassium hydroxide and the like, in a lower alkanol, e.g. methanol, ethanol and the like, or, preferably, in an aqueous solution of a lower alkanol.

This procedure including the preparation of the starting material may be illustrated, for example, by the hydrolysis of ethyl 18-O-methyl-reserpate furnishing the 18-O-methyl-reserpic acid, which may then be esterified with a diazo-compound other than diazoethane, for example, diazomethane and the like.

As previously mentioned, the starting materials used in the above modification of the procedure for the preparation of the compounds of the invention, are new and are intended to be included within the scope of the invention. Especially useful as intermediates are the compounds of the formula:

in which R₅' represents lower alkyl, particularly methyl and the like, and R₄' stands for lower alkoxy, particularly methoxy, whereby the latter is preferably attached to the 10-position or the 11-position, salts, N-oxides or salts of N-oxides. This group of compounds may be represented by 18-O-lower alkyl-reserpic acids, e.g. 18-O-methyl-reserpic acid, 18-O-ethyl-reserpic acid, 18-O-n-propyl-reserpic acid, 18-O-n-butyl-reserpic acid and the like, 18-O-lower alkyl-10-methoxy-deserpic acids, e.g. 10-methoxy-18-O-methyl-deserpic acid, 18-O-ethyl-10-methoxy-deserpic acid, 10-methoxy-18-O-n-propyl-deserpic acid and the like, 18-O-lower alkyl-9-methoxy-deserpic acids, e.g. 9-methoxy-18-O-methyl-deserpic acid and the like, 11-ethoxy-18-O-lower alkyl-deserpic acids, e.g. 11-ethoxy-18-O-methyl-deserpic acid and the like, 18-O-lower alkyl-12-methoxy-deserpic acids, e.g. 12-methoxy-18-O-methyl-deserpic acid and the like. Another preferred group of compounds are the 18-O-lower alkyl-deserpic acids, e.g., 18-O-methyl-deserpic acid, 18-O-ethyl-deserpic acid and the like, as well as, for example, 5-methyl 18-O-methyl-reserpic acid, 6-methyl-18-O-methyl-deserpic acid, 9-methyl-18-O-methyl-deserpic acid, 10-methoxy-18-O-methyl-reserpic acid, 10-chloro-18-O-methyl-deserpic acid, 10-bromo-18-O-methyl-reserpic acid, 18-O-methyl-11-methylmercapto-deserpic acid, 10,11-methylenedioxy-18-O-n-propyl-deserpic acid, 17-desmethoxy-17-ethoxy-18-O-methyl-reserpic acid and the like.

The above starting materials may also be prepared, for example, by alcoholysis of a (16→18)-lactone of 18-hydroxy-17-lower alkoxy-3-epi-allo-yohimbane 16-carboxylic acid, particularly a lactone of the formula:

in which R₂, R₄, R₅ and R₆ have the previously given meaning, a salt, an N-oxide or a salt of an N-oxide thereof, with an alcohol of the formula

in which Ph represents a monocyclic carbocyclic aryl radical and Z stands for hydrogen or lower alkyl, in the presence of an alcoholysis reagent, such as, for example, an alkali metal derivative of such alcohol, or any other suitable reagent, such as one of those previously mentioned, etherifying in a resulting 18-hydroxy-17-lower alkoxy-3-epi-allo-yohimbane 16-carboxylic acid ester, particularly in a resulting compound of the formula:

in which R₂, R₄, R₅ and R₆ have the previously given

meaning, Ph represents monocyclic carbocyclic aryl and Z stands for hydrogen or lower alkyl, a salt, an N-oxide or a salt of an N-oxide thereof, the free hydroxyl group by treatment with a diazo-reagent, such as a diazo-compound of the formula R_3-N_2 , in which R_3 has the previously given meaning, in the presence of a strong inorganic Lewis acid, and converting in a resulting 18-etherified hydroxyl-17-lower alkoxy-3-epi-allo-yohimbane 16-carboxylic acid ester, particularly in a resulting compound of the formula:

in which R_2 , R_3 , R_4 , R_5 , R_6 , Ph and Z have the previously given meaning, the esterified carboxyl into a free carboxyl group, and, if desired, converting a resulting free compound into a salt, an N-oxide or a salt of an N-oxide thereof.

The alcoholysis of the lactone is carried out according to known methods; for example, an alcohol of the formula $Ph-(Z)CH-OH$, in which Ph and Z have the previously indicated meaning, or a solution thereof in an inert solvent, is reacted with an alkali metal, e.g. sodium, potassium and the like, and the resulting reagent is treated with the lactone or a solution thereof. The reaction may proceed under cooling or at room temperature, but may be more readily completed by heating, if necessary, in the atmosphere of an inert gas, e.g. nitrogen.

The monocyclic carbocyclic aryl radical Ph in the above alcohol stands primarily for phenyl; it may also represent substituted phenyl, whereby substituents may be lower alkyl, e.g. methyl, lower alkoxy, e.g. methoxy, or halogeno, e.g. chloro, bromo and the like or any other substituent, which does not hinder the alcoholysis or the subsequent cleavage of the monocyclic carbocyclic aryl-methyl radical. Although Z may represent lower alkyl, e.g. methyl, ethyl, n-propyl and the like, it stands primarily for hydrogen.

Etherification of the free hydroxyl group in 18-position may be carried out as previously shown, i.e. by treatment with an appropriate diazo-reagent in the presence of a strong Lewis acid, e.g. fluoroboric acid and the like.

The esterified carboxyl group may be converted to the free carboxyl group, for example, by hydrogenolysis, which may be carried out by treatment of the ester, preferably in solution, for example, in a lower alkanol, e.g. methanol, ethanol and the like, with hydrogen in the presence of a catalyst, which contains a metal of the eighth group of the periodic system, for example, palladium, e.g. palladium black, or any other suitable catalyst. If necessary, an increased pressure, and/or an elevated temperature may be employed, although normally the reaction proceeds under atmospheric pressure and at room temperature. In order to secure a complete hydrogenolysis, the reaction vessel is agitated to expose the catalyst to the hydrogen. The resulting reaction mixture is freed from the catalyst, for example, by filtration, and the desired product may be isolated according to standard methods, for example, by extraction, crystallization, adsorption and elution, and the like and is purified, for example, by recrystallization and the like.

The ester group may also be cleaved by hydrolysis, for example, by the previously described alkaline hydrolysis or by acid hydrolysis, for example, by treatment with a

hydrohalic acid, e.g. hydrogen bromide and the like, in a lower alkanic acid, e.g. glacial acetic acid and the like.

The intermediates used in the preparation of the 18-etherified hydroxyl-17-lower alkoxy-3-epi-allo-yohimbane 16-carboxylic acid used as the starting materials, particularly the compounds of the formula:

in which R_2 , R_3 , R_4 , R_5 , R_6 , Ph and Z have the previously given meaning, are new and are intended to be included within the scope of the invention. Particularly useful intermediates are the compounds of the formula:

in which R_3' represents lower alkyl, particularly methyl and the like, and R_4' stands for lower alkoxy, especially methoxy and the like, whereby the group R_4' is preferably attached to the 10-position or the 11-position salts, N-oxides or salts of N-oxides thereof. Such compounds are, for example, benzyl 18-O-lower alkyl-reserpates, e.g. benzyl 18-O-methyl-reserpate, benzyl 18-O-ethyl-reserpate and the like, benzyl 18-O-lower alkyl-10-methoxy-deserpipidates, e.g. benzyl 10-methoxy-18-O-methyl-deserpipidate, benzyl 10-methoxy-18-O-n-propyl-deserpipidate and the like. Other highly useful intermediates are, for example, the benzyl 18-O-lower alkyl-deserpipidates, e.g. benzyl 18-O-methyl-deserpipidate, benzyl 18-O-ethyl-deserpipidate and the like, or analogous compounds.

Compounds of the present invention may also be obtained by transesterifying in 18-etherified hydroxy-17-lower alkoxy-3-epi-allo-yohimbane 16-carboxylic acid ester, particularly in compounds of the formula:

in which R_2 , R_3 , R_4 , R_5 and R_6 have the previously given meaning, and R_1 has the above-given meaning and stands also for the group $Ph-(Z)CH-$, in which Ph and Z have the above-given meaning, a salt, an N-oxide or a salt of an N-oxide thereof, the esterified carboxyl group attached to the 16-position, and, if desired, carrying out the optional steps.

The transesterification reaction may be carried out, for

example, by treating the starting material with an alcohol, such as an alcohol of the formula R_1-OH , in which R_1 has the above-given meaning, but stands primarily for lower alkyl, particularly lower alkyl containing from one to four carbon atoms, e.g. methyl, ethyl, propyl, butyl, isobutyl and the like. Alcohols of the formula R_1-OH are, therefore, primarily lower alkanols such as methanol, ethanol, propanol, butanol or isobutanol and the like. Other alcohols, particularly alcohols of the formula R_1-OH are those, in which R_1 represents substituted lower alkyl, such as etherified hydroxy-lower alkyl, e.g. lower alkoxy-lower alkyl, tertiary amino-lower alkyl and the like, whereby the etherified hydroxy and the tertiary amino groups are separated from the hydroxyl group by from two to seven carbon atoms; such alcohols are, for example, 2-methoxyethanol, 2-ethoxyethanol, 3-methoxypropanol, 2-N,N-dimethyl-ethanol, 2-N,N-diethylamino-ethanol and the like.

Transesterification is carried out in the presence of a transesterification catalyst, particularly a basic transesterification catalyst. Such catalysts are, for example, alkoxide ions, as, for example, furnished by alkali metal lower alkanolates, e.g. lithium, sodium or potassium methanolate, ethanolate, n-propanolate, n-butanolate, or isobutanolate and the like, alkaline earth metal lower alkanolates, e.g. barium or strontium methanolate, ethanolate, n-propanolate, n-butanolate, or isobutanolate and the like, or aluminum lower alkanolates, e.g. aluminum methanolate, ethanolate, n-propanolate, isopropanolate, n-butanolate, or isobutanolate and the like. The individual alkanolate compounds are employed together with the corresponding lower alkanol used as the transesterification reagent. Other alcohols such as those of the formula R_1-OH , in which R_1 represents, for example, substituted lower alkyl, such as etherified hydroxy-lower alkyl, e.g. lower alkoxy-lower alkyl and the like, tertiary amino-lower alkyl and the like, may be used in the presence of the corresponding alkali metal, alkaline earth metal or aluminum alcoholates. Other basic transesterification catalysts are, for example, alkali metal cyanides, e.g. potassium cyanide and the like, or strong quaternary ammonium hydroxides, e.g. benzyl-trimethyl-ammonium hydroxide and the like. The transesterification reaction may also be catalyzed by acidic reagents; inorganic acids, such as tungstic acid and the like, or organic acids, such as p-toluene sulfonic acids and the like, may be used.

Apart from the esterifying alcohols, which may simultaneously serve as diluents, other inert solvents may be used in the above-mentioned transesterification reaction; carbocyclic aryl hydrocarbons, e.g. benzene, toluene and the like, are examples of such inert solvents. If necessary, the reaction may be carried out at an elevated temperature, under increased pressure and/or in the atmosphere of an inert gas, e.g. nitrogen.

This method is, therefore, suitable for preparing from compounds of this invention other compounds which are embraced by the generic formula given for the compounds of this invention, and which may not be readily accessible by the other procedures. For example, upon treatment of methyl 18-O-methyl-reserpate with a lower alkanol containing more than one carbon atom, e.g. ethanol, n-propanol and the like, in the presence of a transesterifying reagent, lower alkyl 18-O-methyl-reserpates may be obtained, in which lower alkyl contains more than one carbon atom. Or, a lower alkyl 18-O-methyl-reserpate, in which lower alkyl contains more than one carbon atom, may be treated with methanol in the presence of a transesterifying reagent, such as, for example, sodium methanolate to form the desired methyl 18-O-methyl-reserpate.

The compounds of the present invention may also be prepared, for example, by removing in 18-etherified hydroxy-17-lower alkoxy-3-epi-allo-yohimbane 16-carboxylic acid ester salts, which contain attached to the nitrogen

atom representing the 4-position a substituent, particularly in compounds of the formula:

15 in which R_1 , R_2 , R_3 , R_4 , R_5 and R_6 have the previously given meaning, R represents a group capable of being removed, and $An^{\ominus}$ stands for an anion, the substituent attached to the nitrogen atom of the 4-position, for example, the group R , and, if desired, carrying out the optional steps.

The substituent attached to the nitrogen atom, such as, for example, the radical R in the above formula, may be an aliphatic hydrocarbon radical, such as, for example, lower alkyl, containing preferably from one to four carbon atoms, particularly methyl, as well as ethyl, n-propyl, isopropyl, n-butyl and the like, lower alkenyl, such as allylic lower alkenyl, containing preferably from three to five carbon atoms, e.g. allyl, 2-methyl-allyl, 2-butenyl and the like, or any other suitable aliphatic radical. The group attached to the nitrogen atom of the 4-position, as represented, for example, by the radical R, may also stand for a substituted aliphatic hydrocarbon radical; substituting groups may be, for example, carbocyclic aryl, such as monocyclic or bicyclic carbocyclic aryl, e.g. phenyl, 1-naphthyl, 2-naphthyl and the like, or analogous radicals substituted by additional groups, such as lower alkyl, e.g. methyl, ethyl and the like, lower alkoxy, e.g. methoxy, ethoxy and the like, halogeno, e.g. fluoro, chloro, bromo and the like, nitro, amino, such as N,N-di-lower alkyl-amino, e.g. N,N-dimethylamino and the like, or any other suitable group, which does not impede the departure of the whole group attached to the 4-position. Other substituents attached to the aliphatic hydrocarbon radical may be functional groups, such as, for example, etherified hydroxyl, particularly lower alkoxy, containing preferably from one to four carbon atoms, particularly methoxy, as well as ethoxy, n-propoxy and the like, carbocyclic aryloxy, particularly monocyclic or bicyclic carbocyclic aryl-lower alkoxy, e.g. benzyloxy, diphenyl-methoxy and the like and analogous groups, in which phenyl is substituted by additional substituents, such as those previously mentioned, carbocyclic aryl-lower aliphatic hydrocarbonoxy, such as monocyclic or bicyclic carbocyclic aryl-lower alkoxy, e.g. phenylmercapto and the like and phenylmercapto, in which phenyl is substituted by the aforementioned substituents, carbocyclic aryl-lower aliphatic hydrocarbon-mercapto, such as monocyclic or bicyclic carbocyclicmercapto, e.g. phenylmercapto and the like, and analogous groups, in which the carbocyclic aryl radical is substituted by the aforementioned substituents, halogeno atoms, e.g. chloro, bromo and the like, carbolower alkoxy, e.g. carbomethoxy, carbethoxy and the like, or any other suitable functional group.

The aliphatic hydrocarbon group, to which the above-mentioned substituents are added, are primarily repre-

sented by lower alkylene radicals, above all by the methylene radical, as well as by 1,1-ethylene, 1,2-ethylene, 1,1-propylene and the like. Preferred substituted aliphatic hydrocarbon radicals attached to the nitrogen atom of the 4-position, as particularly represented by the group R in the above formula, are, for example, monocyclic carbocyclic aryl-lower alkyl, particularly monocyclic carbocyclic aryl-methyl, e.g. benzyl, diphenylmethyl, trityl and the like, or 1-monocyclic carbocyclic aryl-ethyl, e.g. 1-phenylethyl and the like, lower alkoxy-lower alkyl, particularly lower alkoxy-methyl, e.g. methoxymethyl, ethoxymethyl, n-propyloxymethyl, isopropyloxymethyl and the like, monocyclic carbocyclic aryl-lower alkoxy-lower alkyl, particularly monocyclic carbocyclic aryl-lower alkoxy-methyl, e.g. benzyloxymethyl and the like, lower alkyl-mercaptop-lower alkyl, particularly lower alkyl-mercaptopmethyl, e.g. methylmercaptopmethyl, ethylmercaptopmethyl and the like, monocyclic carbocyclic aryl-lower alkyl-mercaptop-lower alkyl, especially monocyclic carbocyclic aryl-lower alkyl-mercaptopmethyl, e.g. benzylmercaptopmethyl and the like, halogeno-lower alkyl, primarily halogenomethyl, e.g. chloromethyl, bromomethyl and the like, carbo-lower alkoxy-lower alkyl, particularly carbo-lower alkoxy-methyl, e.g. carbomethoxymethyl, carbethoxymethyl and the like.

The anion of the salts used as the starting materials, especially the anion represented by the group $An^{\ominus}$ in the above formula, stands primarily for the anion of a strong inorganic, especially mineral, acid, e.g. hydrochloric, hydrobromic, hydriodic, sulfuric, fluoboric acid and the like, or of a strong organic, particularly a strong organic sulfonic acid, e.g. p-toluene sulfonic acid and the like.

The group attached to the nitrogen atom of the 4-position, as represented, for example, by the group R in the above formula, may be removed according to methods, the selection of which depends primarily on the nature of this group.

The substituent may be cleaved off by pyrolysis at an elevated temperature, preferably under reduced pressure, and, if desired, in a high-boiling solvent and/or in the atmosphere of an inert gas, e.g. nitrogen.

Specifically substituted groups may be removed by other procedures. For example, monocyclic carbocyclic aryl-methyl or 1-monocyclic carbocyclic aryl-ethyl groups, such as benzyl, diphenylmethyl, trityl, 1-phenylethyl and the like, as well as monocyclic carbocyclic aryl-lower alkoxy-methyl, e.g. benzyloxymethyl, diphenylmethoxymethyl and the like, or any other analogous substituent, may be removed by hydrogenolysis, for example, by treatment with hydrogen in the presence of a catalyst containing a metal of the eighth group of the periodic system, e.g. nickel, palladium and the like. Other groups, such as, for example, etherified hydroxy-methyl, such as lower alkoxy-methyl, e.g. methoxymethyl and the like, or any other etherified hydroxy-methyl group, e.g. benzyloxymethyl and the like, halogenomethyl, e.g. chloromethyl and the like, carbo-lower alkoxy-methyl, e.g. carbomethoxymethyl, carbethoxymethyl and the like, may be removed by hydrolysis, for example, by treatment with a dilute inorganic acid, such as, for example, hydrochloric, sulfuric acid and the like. Still other groups, representing, for example, the substituent R in the above formula, particularly etherified mercapto-methyl, such as lower alkyl-mercaptopmethyl, e.g. methylmercaptopmethyl, ethylmercaptopmethyl and the like, carbocyclic aryl-mercaptopmethyl, particularly monocyclic aryl-mercaptopmethyl, e.g. phenylmercaptopmethyl and the like, or carbocyclic aryl-lower aliphatic hydrocarbon-mercaptopmethyl, such as monocyclic carbocyclic aryl-lower alkyl-mercaptopmethyl, e.g. benzylmercaptopmethyl and the like, may be removed by desulfurization in the presence of a hydrogenation catalyst, particularly a catalyst containing a metal of the eighth group of the periodic system, e.g. Raney nickel, palladium black and the like.

The starting materials used in the above procedure may

be obtained according to different methods. For example, an 18-hydroxy-17-lower alkoxy-3-epi-allo-yohimbane 16-carboxylic acid ester, particularly a compound of the formula:

in which R_1 , R_2 , R_4 , R_5 and R_6 have the previously given meaning, or a salt thereof, may be treated with a reactive ester of an aliphatic hydroxy-hydrocarbon compound or a reactive ester of a substituted aliphatic hydroxy-hydrocarbon compound, which contains as a substituent one of the above-mentioned groups, represented, for example, by the compound of the formula $R-OH$, in which R has the previously given meaning, and, if necessary, the 18-hydroxyl group in a resulting 18-hydroxy-17-lower alkoxy-3-epi-allo-yohimbane 16-carboxylic acid ester salt, which contains an aliphatic hydrocarbon or a substituted aliphatic hydrocarbon attached to the nitrogen atom of the 4-position, particularly in a resulting compound of the formula:

in which R_1 , R_2 , R_4 , R_5 , R_6 , R and $An^{\ominus}$ have the previously given meaning, may be etherified and the desired starting materials may be isolated.

Reactive esters of aliphatic hydroxy-hydrocarbon and substituted aliphatic hydroxy-hydrocarbon compounds are particularly those with strong inorganic acids, particularly strong mineral acids, e.g. hydrochloric, hydrobromic, hydriodic, sulfuric acid and the like, or with strong organic acids, such as organic sulfonic acids, e.g. p-toluene sulfonic acid and the like. The reaction is carried out in the absence or presence of an inert solvent, under cooling, at room temperature or at an elevated temperature, and, if necessary, under pressure or in the atmosphere of an inert gas, e.g. nitrogen.

The etherification of the free hydroxyl group in the 18-position may occur simultaneously with the introduction of a removable group into the 4-position. Or, a free 18-hydroxyl group in a resulting compound may then be etherified as previously shown, for example, by treatment with an aliphatic diazo-hydrocarbon, particularly a lower diazo-alkane, such as diazomethane and the like, or a substituted aliphatic diazo-hydrocarbon, such as an etherified hydroxy-lower diazo-alkane and the like, if necessary, in the presence of a strong Lewis acid, such as fluoboric acid and the like.

Introduction of the desired group into the 4-position of an 18-hydroxy-17-lower alkoxy-3-epi-allo-yohimbane 16-carboxylic acid ester or a salt thereof may occur by treatment with a diazo-reagent, such as an aliphatic diazo-hydrocarbon, particularly a lower diazoalkane, especially diazomethane and the like, or a substituted aliphatic diazo-hydrocarbon. The reaction is carried out in the presence

of a Lewis acid, such as, for example, fluoboric acid and the like; under these conditions the free hydroxyl group attached to the 18-position may be etherified simultaneously, particularly, if an excess of the diazo-reagent is used.

The starting materials used in the above reaction are new and are intended to be included within the scope of the invention. Particularly useful as starting materials are compounds of the formula:

in which R_1 , R_2 , R_3 , R_4 , R_5 , R_6 , R and An^- have the previously given meaning. This group may be illustrated by the compounds of the formula:

in which each of the radicals R_1' and R_3' stands for lower alkyl, particularly methyl and the like R_1' represents lower alkoxy, especially methoxy and the like, whereby R_1' is preferably attached to the 10-position or the 11-position, R' stands for lower alkyl, especially methyl and the like, monocyclic carbocyclic aryl-lower alkyl, particularly monocyclic carbocyclic aryl-methyl, e.g. benzyl and the like, or 1-monocyclic carbocyclic aryl-methyl, e.g. 1-phenylethyl and the like, etherified hydroxy-lower alkyl, such as lower alkoxy-lower alkyl, particularly lower alkoxy-methyl, e.g. methoxymethyl and the like, monocyclic carbocyclic aryl-lower alkoxy-lower alkyl, particularly monocyclic carbocyclic aryl-lower alkoxy-methyl, e.g. benzylmethoxymethyl, diphenyloxymethyl and the like, lower alkyl-mercaptop-lower alkyl, particularly lower alkyl-mercaptopmethyl, e.g. methylmercaptopmethyl and the like, halogeno-lower alkyl, particularly halogenomethyl, e.g. chloromethyl and the like, or carbo-lower alkoxy-lower alkyl, such as carbo-lower alkoxy-methyl, e.g. carbomethoxy-methyl and the like, and An^- represents the anion of a strong acid, primarily a strong inorganic acid. Another preferred group of starting materials may be represented by the compounds of the formula:

in which R_1' , R_3' , R' and An^- have the above-given meaning.

Specific starting materials, useful in the above-described procedure, particularly the compounds of the formula:

in which R_1 , R_2 , R_3 , R_4 , R_5 , R_6 , R and An^- have the previously given meaning, with the proviso that the groups R_1 , R_3 and R have the same meaning, may also be obtained, for example, by treating a (16→18)-lactone of an 18-hydroxy-17-lower alkoxy-3-epi-allo-yohimbane 16-carboxylic acid, particularly a compound of the formula:

in which R_2 , R_4 , R_5 and R_6 have the previously given meaning, or a salt thereof, with a tri-substituted oxonium fluoborate and recovering the desired compound.

The above-mentioned tri-substituted oxonium fluoborate reagent may be represented, for example, by tri-lower alkyl-oxonium fluoborate, especially by trimethyl-oxonium fluoborate, as well as triethyl oxonium fluoborate and the like. The reaction with this reagent is preferably carried out in the presence of an inert solvent, if necessary, at an elevated temperature, and, if necessary, under pressure or in the atmosphere of an inert gas, e.g. nitrogen.

The above reaction, i.e. treatment of a (16→18)-lactone of 18-hydroxy-17-lower alkoxy-3-epi-allo-yohimbane 16-carboxylic acid with a tri-substituted oxonium fluoborate, may also yield the desired 18-etherified hydroxy-17-lower alkoxy-3-epi-allo-yohimbane 16-carboxylic acid esters directly as a by-product, particularly the 17,18-di-lower alkoxy-3-epi-allo-yohimbane 16-carboxylic acid lower alkyl esters, such as those of the formula:

in which R_2 , R_4 , R_5 and R_6 have the previously given meaning, and the radicals R_1' and R_3' representing lower alkyl, have the same meaning, whenever the lactone, used as the starting material, is reacted with a tri-lower alkyl-oxonium fluoborate. The formation of the compounds of this in-

vention according to the above procedure is, therefore, also included within the scope of the invention; it may be illustrated by the reaction of the (16-18)-lactone of reserpic acid with trimethyl oxonium fluoborate, preferably in the presence of a diluent, and isolation of the desired methyl 18-O-methyl-reserpate.

An additional procedure useful for the preparation of compounds of the present invention comprises removing in 18-etherified hydroxyl-17-lower alkoxy-3-epi-allo-yohimbane 16-carboxylic acid N-oxides, particularly in compounds of the formula:

in which R₁, R₂, R₃, R₄, R₅ and R₆, or salts thereof, the oxygen atom attached to the nitrogen atom in the 4-position, and, if desired, converting a resulting salt into the free compound, and/or, if desired, converting a resulting compound into a salt thereof.

The oxygen atom may be removed by treatment with a reducing reagent, for example, with hydrogen in the presence of a catalyst, which contains a metal of the eighth group of the periodic system, such as nickel, platinum, palladium and the like, e.g. Raney nickel, platinum oxide and the like, or with nascent hydrogen, as generated, for example, by heavy metals, e.g. iron, zinc, tin and the like, in the presence of acids, e.g. acetic acid and the like, or with any other appropriate reducing reagent or method.

The starting materials used in the above reaction may be prepared, for example, by etherifying in an 18-hydroxy-17-lower alkoxy-3-epi-allo-yohimbane 16-carboxylic acid ester N-oxide, particularly in a compound of the formula:

in which R₁, R₂, R₄, R₅ and R₆ have the previously given meaning, or a salt thereof, the 18-hydroxyl group. This etherification may be carried out by treatment with an aliphatic diazo-hydrocarbon, such as lower diazo-alkane, particularly diazomethane and the like, or a substituted aliphatic diazo-hydrocarbon, preferably in the presence of a strong Lewis acid, e.g. fluoboric acid and the like, in the presence of a suitable solvent according to the previously outlined method, or by treatment with any other etherification reagent suitable for the etherification of a secondary hydroxyl group.

The N-oxides used as intermediates for the preparation of the starting materials are known, or, if new, may be prepared according to methods used for the preparation of known compounds.

The compounds of the present invention may also be prepared by removing in 18-etherified hydroxyl-17-lower alkoxy-allo-yohimbane 16-carboxylic acid esters, in which a

double bond extends from the 3-position or salts of such compounds, particularly in compounds of the formula:

in which R₁, R₂, R₃, R₄, R₅ and R₆ have the previously given meaning, and in which a double bond extends from the 3-position, or salts thereof, the double bond extending from the 3-position by reduction and, if desired, carrying out the optional steps.

In the above starting materials the double bond extends probably from the 3-position to the 14-position, or, in the salts thereof, from the 3-position to the 4-position.

The anion in the above-mentioned salts stands primarily for the anion of a strong inorganic acid, particularly a mineral acid, such as a hydrohalic acid, e.g. hydrochloric, hydrobromic acid and the like, or phosphoric acid, a halogenophosphoric acid, e.g. chlorophosphoric acid and the like, or perchloric acid or any other suitable acid. It may also represent the anion of an organic acid; a salt with an organic acid may be present whenever a solution of the starting material in an organic acid, e.g. acetic acid and the like, is used in the above-described removal procedure.

The removal of the double bond may be carried out with the help of a reduction procedure, particularly by treating a solution of the starting material in an acid, such as, for example, acetic acid (preferably in the form of aqueous acetic acid), perchloric acid and the like, with a metal. Together with the acid the metal furnishes the reducing reagent capable of reducing the double bond; zinc, in the presence of an acid, e.g. acetic, perchloric acid and the like, yields a very useful reducing reagent. Zinc in the presence of perchloric acid, which may be used in an aqueous mixture or in admixture with another acid, e.g. acetic acid, represents the preferred reagent; this reagent is particularly suitable because the rate of reduction is fast and any contact of the starting material, as well as the reduction product with the acidic medium can be kept to a minimum. Organic diluents, such as ethers, e.g. tetrahydrofuran, p-dioxan and the like, lower alkanes, e.g. acetone and the like, or any other suitable solvent may be present as additional diluents, if desired, together with water. The reduction may be carried out at room temperature, or, if necessary, under cooling or at an elevated temperature.

The product of the reduction procedure may be isolated, for example, by neutralizing the reaction mixture with an alkaline reagent, e.g. ammonia and the like, if desired, after removing the solvent or part of it, and extracting the organic material with a solvent, e.g. methylene chloride and the like, or by any other suitable isolation method.

The above procedure may be illustrated, for example, by the treatment of methyl Δ^3 -dehydro-18-O-methyl-reserpate, in which the double bond probably extends from the 3-position to the 14-position, or a methyl Δ^3 -dehydro-18-O-methyl-reserpate salt, in which the double bond extends from the 3-position to the 4-position, with zinc in the presence of an acid, e.g. acetic, perchloric acid and the like, and the isolation of the desired methyl 18-O-methyl-reserpate.

The starting material, which is used in the above procedure and has the previously given formula, is new and is intended to be included within the scope of the present

invention. A preferred group of starting materials has the previously given formula and is particularly represented by the compounds of the formula:

in which each of the groups R_1' and R_3' stands for lower alkyl, containing preferably from one to four carbon atoms, particularly methyl, as well as ethyl, n-propyl, isopropyl, n-butyl and the like, and R_4' stands for lower alkoxy, containing preferably from one to four carbon atoms, particularly methoxy, as well as ethoxy, n-propoxy, n-butyloxy and the like, whereby R_4' is preferably attached to the 10-position or the 11-position, and in which a double bond extends from the 3-position to the 14-position, and salts of such compounds, in which a double bond extends from the 3-position to the 4-position, especially salts containing as the anion portion an anion derived from an inorganic, particularly a mineral, acid, such as one of those mentioned hereinabove. Specific examples of this group of starting materials are, for example, lower alkyl Δ^3 -dehydro-18-O-lower alkyl-reserpates, e.g. methyl Δ^3 -dehydro-18-O-methyl-reserpate, methyl Δ^3 -dehydro-18-O-ethyl-reserpate, methyl Δ^3 -dehydro-18-O-n-propyl-reserpate, methyl Δ^3 -dehydro-18-O-n-butyl-reserpate, ethyl Δ^3 -dehydro-18-O-methyl-reserpate, ethyl Δ^3 -dehydro-18-O-ethyl-reserpate, n-propyl Δ^3 -dehydro-18-O-methyl-reserpate, n-butyl Δ^3 -dehydro-18-O-methyl-reserpate and the like, lower alkyl Δ^3 -dehydro-18-O-lower alkyl-10-methoxy-deserpipates, e.g. methyl Δ^3 -dehydro-10-methoxy-18-O-methyl-deserpipate, methyl Δ^3 -dehydro-18-O-ethyl-10-methoxy-deserpipate, methyl Δ^3 -dehydro-18-O-n-butyl-10-methoxy-deserpipate, ethyl Δ^3 -dehydro-10-methoxy-18-O-methyl-deserpipate, ethyl Δ^3 -dehydro-10-methoxy-18-O-n-propyl-deserpipate, n-propyl Δ^3 -dehydro-10-methoxy-18-O-methyl-deserpipate, isopropyl Δ^3 -dehydro-10-methoxy-18-O-methyl-deserpipate and the like, in which the double bond probably extends from the 3-position to the 14-position, and salts of such compounds, in which the double bond extends from the 3-position to the 4-position, as well as lower alkyl Δ^3 -dehydro-18-O-lower alkyl-9-methoxy-reserpate, e.g. methyl Δ^3 -dehydro-9-methoxy-18-O-methyl-deserpipate, methyl Δ^3 -dehydro-18-O-ethyl-9-methoxy-deserpipate, ethyl Δ^3 -dehydro-9-methoxy-18-O-methyl-deserpipate and the like, lower alkyl Δ^3 -dehydro-11-ethoxy-18-O-lower alkyl-deserpipate, e.g. methyl Δ^3 -dehydro-11-ethoxy-18-O-methyl-deserpipate, methyl Δ^3 -dehydro-11-ethoxy-18-O-ethyl-deserpipate, n-propyl Δ^3 -dehydro-11-ethoxy-18-O-methyl-deserpipate and the like, lower alkyl Δ^3 -dehydro-18-O-lower alkyl-12-methoxy-deserpipate, e.g. methyl Δ^3 -dehydro-12-methoxy-18-O-methyl-deserpipate, ethyl Δ^3 -dehydro-12-methoxy-18-O-n-propyl-deserpipate and the like, in which the double bond probably extends from the 3-position to the 14-position, and salts of these compounds, in which the double bond extends from the 3-position to the 4-position.

Another group of very useful intermediates are, for example, lower alkyl Δ^3 -dehydro-18-O-lower alkyl-deserpipates, e.g. methyl Δ^3 -dehydro-18-O-methyl-deserpipate, methyl Δ^3 -dehydro-18-O-ethyl-deserpipate, methyl Δ^3 -dehydro-18-O-n-butyl-deserpipate, ethyl Δ^3 -dehydro-18-O-methyl-deserpipate, ethyl Δ^3 -dehydro-18-O-n-propyl-deserpipate, n-propyl Δ^3 -dehydro-18-O-methyl-deserpipate, isopropyl Δ^3 -dehydro-18-O-methyl-deserpipate, n-butyl Δ^3 -de-

hydro-18-O-methyl-deserpipate and the like, in which the double bond probably extends from the 3-position to the 14-position, and the salts of these compounds, in which the double bond extends from the 3-position to the 4-position. 5 Salts of the above-mentioned compounds contain as anions those of inorganic, particularly mineral, acids, such as hydrohalic acids, e.g. hydrochloric, hydrobromic acid and the like, phosphoric acid, halogeno-phosphoric acids, e.g. chlorophosphoric acid and the like, or perchloric acid or 10 any other suitable inorganic acid, as well as organic acids, e.g. acetic acid and the like.

The above-mentioned starting materials may be prepared, for example, by etherifying in an 18-hydroxy-17-lower alkoxo-3-oxo-2,3-seco-allo-yohimbane 16-carboxylic acid ester, particularly in a compound of the formula:

in which R_1 , R_2 , R_4 , R_5 and R_6 have the previously given meaning, the free hydroxyl group in the 18-position, and converting the resulting 18-etherified hydroxy-17-lower alkoxo-3-oxo-2,3-seco-allo-yohimbane 16-carboxylic acid ester, particularly the resulting compound of the formula:

in which R_1 , R_2 , R_3 , R_4 , R_5 and R_6 have the previously given meaning, into the desired starting material by ring closure, and, if desired, converting a resulting salt into the free base.

The etherification of the free hydroxyl group of the 18-position in the 2,3-seco-compound can be carried out according to known etherification procedures. For example, treatment with an aliphatic diazo-hydrocarbon, such as a lower diazo-alkane, particularly diazomethane and the like or a substituted aliphatic diazo-hydrocarbon, for example, as in the previously described procedure in the presence of a Lewis acid, such as, for example, fluoroboric acid and the like, affords the desired etherification. The latter may also be carried out by treatment with other reagents suitable for the etherification of a secondary hydroxyl group. Such reagents are, for example, reactive esters formed by aliphatic hydroxy-hydrocarbon compounds, such as lower alkanols, particularly methanol, as well as ethanol and the like, or by substituted aliphatic hydroxy-hydrocarbon compounds with strong acids, such as inorganic acids, e.g. hydrochloric, hydrobromic, hydriodic, sulfuric acid and the like, or with organic acids, particularly strong organic sulfonic acids, e.g. p-toluene sulfonic acid and the like, which reagents are preferably used in the presence of reagents facilitating the etherification procedure. Especially useful are 75 di-lower alkyl sulfates, particularly dimethyl sulfate, as

well as diethyl sulfate and the like, which reagents are preferably used in the presence of a base, such as an alkali metal hydroxide, e.g. sodium hydroxide, potassium hydroxide and the like, lower alkyl halides, especially methyl chloride, methyl bromide, methyl iodide and the like, as well as ethyl, n-propyl or n-butyl chloride, bromide or iodide and the like, which reagents are preferably used in the presence of a basic reagent, such as, for example, silver oxide and the like, or any other suitable etherification procedure.

Ring closure of the resulting ether compound can be achieved, for example, by treatment with an acidic ring closing reagent, for example, phosphoric acids, e.g. polyphosphoric acid and the like, phosphorus halides, e.g. phosphorus trichloride, phosphorus pentachloride, or advantageously phosphorus oxyhalides, e.g. phosphorus oxychloride and the like.

The conversion of a resulting salt, in which the double bond extends from the 3-position to the 4-position, particularly of a salt having the partial formula:

in which R_8 has the previously given meaning, and $An^{\ominus}$ represents an anion, derived, for example, from the acidic ring closing reagent, into the free base, in which the double bond extends probably from the 3-position to the 14-position, particularly into a compound having probably the partial formula:

in which R_8 has the previously given meaning, can be carried out according to known methods, for example, by treatment of the salt with a base, particularly ammonia, as well as an alkali metal carbonate, e.g. sodium, potassium carbonate or hydrogen carbonate and the like. Under acidic conditions, as, for example, prevailing in the reduction procedure, the free base forms a salt, in which the double bond extends from the 3-position to the 4-position.

The 18-etherified hydroxy-17-lower alkoxy-3-oxo-2,3-seco-allo-yohimbane 16-carboxylic acid esters, which are used as intermediates for the preparation of the starting materials, particularly the compounds of the following formula:

in which R_1 , R_2 , R_3 , R_4 , R_5 and R_6 have the previously

given meaning, are new and are intended to be included within the scope of the present invention. Particularly useful as intermediates are the compounds of the formula:

in which each of the radicals R_1' and R_3' represents lower alkyl, preferably containing from one to four carbon atoms, especially methyl, as well as ethyl, n-propyl, iso-

- 20 atoms, especially methyl, as well as ethyl, n-propyl, iso-propyl, n-butyl, secondary butyl and the like, and R₄' represents lower alkoxy, especially lower alkoxy containing from one to four carbon atoms, particularly methoxy, as well as ethoxy, n-propoxy, isopropoxy, n-butyloxy and the like, whereby such lower alkoxy group R₄' is preferably attached to the 10-position or the 11-position. Specific compounds of this group are, for example, lower alkyl 18-O-lower alkyl-3-oxo-2,3-seco-reserpates, e.g. methyl 18-O-methyl-3-oxo-2,3-seco-reserpate, methyl 18-O-ethyl-3-oxo-2,3-seco-reserpate, methyl 18-O-n-propyl-3-oxo-2,3-seco-reserpate, methyl 18-O-n-butyl-3-oxo-2,3-seco-reserpate, methyl 18-O-isobutyl-3-oxo-2,3-seco-reserpate, ethyl 18-O-methyl-3-oxo-2,3-seco-reserpate, ethyl 18-O-n-propyl-3-oxo-2,3-seco-reserpate, n-propyl 18-O-methyl-3-oxo-2,3-seco-reserpate, n-propyl 18-O-ethyl-3-oxo-2,3-seco-reserpate, isopropyl 18-O-methyl-3-oxo-2,3-seco-reserpate, isopropyl 18-O-n-butyl-3-oxo-2,3-seco-reserpate, n-butyl 18-O-methyl-3-oxo-2,3-seco-reserpate and the like, or lower alkyl 18-O-lower alkyl-10-methoxy-3-oxo-2,3-seco-deserpидates, e.g. methyl 10-methoxy-18-O-methyl-3-oxo-2,3-seco-deserpидate, methyl 18-O-ethyl 10-methoxy-3-oxo-2,3-seco-deserpидate, methyl 10-methoxy-18-O-n-propyl-3-oxo-2,3-seco-deserpидate, methyl 18-O-n-butyl-10-methoxy-3-oxo-2,3-seco-deserpидate, ethyl 10-methoxy-18-O-methyl-3-oxo-2,3-seco-deserpидate, ethyl 18-O-ethyl-10-methoxy-3-oxo-2,3-seco-deserpидate, n-propyl 10-methoxy-18-O-methyl-3-oxo-2,3-seco-deserpидate, isopropyl 10-methoxy-18-O-methyl-3-oxo-2,3-seco-deserpидate and the like, as well as lower alkyl 18-O-lower alkyl-9-methoxy-3-oxo-2,3-seco-deserpидates, e.g. methyl 9-methoxy-18-O-methyl-3-oxo-2,3-seco-deserpидate, methyl 18-O-ethyl-9-methoxy-3-oxo-2,3-seco-deserpидate, ethyl 9-methoxy-18-O-methyl-3-oxo-2,3-seco-deserpидate and the like, lower alkyl 11-ethoxy-18-O-lower alkyl-3-oxo-2,3-seco-deserpидates, e.g. methyl 11-ethoxy-18-O-methyl-3-oxo-2,3-seco-deserpидate, methyl 11-ethoxy-18-O-n-propyl-3-oxo-2,3-seco-deserpидate and the like, lower alkyl 18-O-lower alkyl-12-methoxy-3-oxo-2,3-seco-deserpидates, e.g. methyl 12-methoxy-18-O-methyl-3-oxo-2,3-seco-deserpидate, ethyl 12-methoxy-18-O-methyl-3-oxo-2,3-seco-deserpидate and the like. Another group of highly useful intermediates are the lower alkyl 18-O-lower alkyl-3-oxo-2,3-seco-deserpидates, e.g. methyl 18-O-methyl-3-oxo-2,3-seco-deserpидate, methyl 18-O-ethyl-3-oxo-2,3-seco-deserpидate, methyl 18-O-n-propyl-3-oxo-2,3-seco-deserpидate, methyl 18-O-n-butyl-3-oxo-2,3-seco-deserpидate, methyl 18-O-isobutyl-3-oxo-2,3-seco-deserpидate, ethyl 18-O-ethyl-3-oxo-2,3-seco-deserpидate, n-propyl 18-O-n-propyl-3-oxo-2,3-seco-deserpидate, isopropyl 18-O-methyl-3-oxo-2,3-seco-deserpидate, n-butyl 18-O-methyl-3-oxo-2,3-seco-deserpидate and the like.

The intermediates used for the preparation of the starting materials of the described procedure may also be obtained, for example, by etherifying in an ester of 3β -hy-

droxy-2 α -lower alkoxy-7-oxo-1 α ,2 β ,3 α ,4,7,8,9 α ,10 α -octahydronaphthalene-1 β -carboxylic acid of the formula:

in which R₂, as well as R₁, have the previously given meaning, whereby R₁ represents particularly lower alkyl, particularly methyl, as well as ethyl, n-propyl, isopropyl, n-butyl and the like, the hydroxyl group in the 3 β -position according to known methods used for the etherification of a secondary hydroxyl group, for example, by treatment with a diazo compound, such as a lower diazo-alkane, particularly diazomethane and the like, in the presence of an etherification catalyst, particularly fluoboric acid and the like, as previously described. The resulting α , β -ketone is then oxidized, for example, with osmium tetroxide, in an aqueous solution, followed by treatment with sodium chlorate, to form an ester of 5 α ,6 α -dihydroxy-3 β -etherified hydroxy-2 α -lower alkoxy-7-oxo-1 α ,2 β ,3 α ,4,5 β ,6 β ,7,8,9 α ,10 α - decahydronaphthalene - 1 β - carboxylic acid having the formula:

in which R₁, R₂ and R₃ have the above-given meaning, which diol is then oxidatively split, for example, by treatment with periodic acid hydrate in an aqueous medium, to a monoester of the 5 β -aldehyde-3 β -etherified hydroxy-6 β - carboxymethyl - 2 α - lower alkoxy-1 α ,2 β ,3 α ,4,5 α ,6 α -hexahydrobenzene-1 β -carboxylic acid of the formula:

in which R₁, R₂ and R₃ have the previously given meaning. The free carboxyl group of the carboxymethyl portion is then esterified, for example, with a lower diazo-hydrocarbon, such as a lower diazoalkane, especially diazomethane, as well as diazoethane and the like, to form the desired diesters of 5 β -aldehyde-3 β -etherified hydroxy-6 β -carboxymethyl-2 α -lower alkoxy-1 α ,2 β ,3 α ,4,5 α ,6 α -hexahydrobenzene-1 β -carboxylic acid, having the formula:

in which R₁, R₂ and R₃ have the previously given meaning, and R₁'' represents, for example, lower alkyl, particularly methyl, as well as ethyl and the like. This com-

ound is then reacted with a tryptamine, particularly a tryptamine compound of the formula:

in which R₄, R₅ and R₆ have the above-given meaning, preferably in solution with an inert solvent, e.g. benzene and the like, to yield a $\Delta^{4(21)}$ -18-etherified hydroxy-3,17-di-lower alkoxy-3-oxo-2,3:3,4-bis-seco-allo-yohimbane 16-carboxylic acid ester, particularly a compound of the formula:

in which R₁, R₁'', R₂, R₃, R₄, R₅ and R₆ have the previously given meaning. Upon treatment with a reducing reagent, for example, with a borohydride, e.g. sodium borohydride and the like, in an inert solvent, such as a lower alkanol, e.g. methanol, ethanol and the like, and, if necessary, in the presence of an activator, e.g. aluminum chloride and the like, the Schiff-base type double bond is reduced and an 18-etherified hydroxy-3,17-di-lower alkoxy-3-oxo-2,3:3,4 - bis - seco-allo-yohimbane 16-carboxylic acid ester, particularly a compound of the formula:

in which R₁, R₁'', R₂, R₃, R₄, R₅ and R₆ have the previously given meaning, is formed, in which the esterified carboxyl groups may be partially or totally hydrolyzed. Hydrolyzed carboxyl groups may subsequently be re-esterified (for example, with a lower aliphatic diazo-hydrocarbon, such as a lower diazoalkane, particularly diazomethane, as well as diazoethane and the like, or any other suitable diazo-reagent). Treatment of the ester with a dehydrating agent, such as, for example, a carboxylic acid anhydride, e.g. acetic acid anhydride and the like, causes ring closure to the desired 18-etherified hydroxy-17-lower alkoxy-3-oxo-2,3-seco-allo-yohimbane 16-carboxylic acid ester, which is used as the starting material in the above reaction and which may be illustrated by the compounds of the formula:

in which R_1 , R_2 , R_3 , R_4 , R_5 and R_6 have the previously given meaning.

In the above described procedure for the manufacture of intermediates a number of new compounds, having useful properties as intermediates, are being formed, which are intended to be included within the scope of the present invention.

Important intermediates, are, for example, compounds of the formula:

10

in which R_1 , R_2 and R_3 have the above-given meaning. Particularly useful intermediates are the lower alkyl 2α -methoxy- 7α -oxo- 3β -lower alkoxy- $1\alpha,2\beta,3\alpha,4,7,8,9\alpha,10\alpha$ -octahydronaphthalene- 1β -carboxylates, in which lower alkyl, containing from one to four carbon atoms, represents primarily methyl, as well as ethyl, n-propyl and the like, and lower alkoxy, containing from one to four carbon atoms, stands primarily for methoxy, as well as ethoxy, n-propoxy and the like, particularly methyl $2\alpha,3\beta$ -di-methoxy- 7α -oxo- $1\alpha,2\beta,3\alpha,4,7,8,9\alpha,10\alpha$ -octahydronaphthalene- 1β -carboxylate and the like.

Other important and new intermediates are compounds of the formula:

15

in which R_1 , R_1'' , R_2 and R_3 have the previously given meaning. This group of intermediates is represented by lower alkyl 5β -aldehydo- 6β -carbo-lower alkoxy-methyl- 2α -methoxy- 3β -lower alkoxy- $1\alpha,2\beta,3\alpha,4,5\alpha,6\alpha$ -hexahydrobenzene- 1β -carboxylate, in which lower alkyl, containing from one to four carbon atoms, represents primarily methyl, as well as ethyl, n-propyl and the like, and lower alkoxy, containing from one to four carbon atoms, stands particularly for methoxy, as well as ethoxy, n-propoxy and the like, and especially by methyl 5β -aldehydo- 6β -carbomethoxy-methyl- $2\alpha,3\beta$ -dimethoxy- $1\alpha,2\beta,3\alpha,4,5\alpha,6\alpha$ -hexahydrobenzene- 1β -carboxylate and the like.

Additional intermediates useful in the preparation of the starting material and thus in the process of the invention are the $\Delta^4(21)$ -etherified-hydroxy- $3,17$ -di-lower alkoxy- 3 -oxo- $2,3;3,4$ -bis-seco-allo-yohimbane 16 -carboxylic acid esters, particularly the compounds of the formula:

35

40

in which R_1 , R_1'' , R_2 , R_3 , R_4 , R_5 and R_6 have the previously given meaning, or salts thereof. Each of the radicals R_1 , R_1'' and R_3 represents primarily lower alkyl, containing from one to four carbon atoms, especially methyl, as well as ethyl, n-propyl and the like. This group of intermediates may be represented by compounds of the formula:

60

65

in which the radicals R_1' and R_1'' have the same meaning and stand for lower alkyl, containing preferably from one to four carbon atoms, particularly form ethyl, as well as ethyl, n-propyl and the like, R_3' represents lower alkyl, containing preferably from one to four carbon atoms, especially methyl, as well as ethyl and the like, and R_4' represents lower alkoxy, containing preferably from one to four carbon atoms, particularly methoxy, as well as ethoxy, n-propoxy and the like, whereby the lower

alkyl $5\alpha,6\alpha$ -dihydroxy- 2α -methoxy- 17 -oxo- 3β -lower alkoxy- $1\alpha,2\beta,3\alpha,4,5\beta,6\beta,7,8,9\alpha,10\alpha$ -decahydronaphthalene- 1β -carboxylates, in which lower alkyl, containing from one to four carbon atoms, represents primarily methyl, as well as ethyl, n-propyl and the like, and lower alkoxy, containing from one to four carbon atoms, stands particularly for methoxy, as well as ethoxy, n-propoxy and the like, especially by methyl $5\alpha,6\alpha$ -dihydroxy- $2\alpha,3\beta$ -di-lower alkoxy- 7 -oxo- $1\alpha,2\beta,3\alpha,4,5\beta,6\beta,7,8,9\alpha,10\alpha$ -decahydronaphthalene- 1β -carboxylate and the like.

A further series of important intermediates are the compounds of the formula:

70

in which R_1 , R_2 and R_3 have the previously given meaning. This group of intermediates may be represented by lower alkyl 5β -aldehydo- 6β -carboxymethyl- 2α -methoxy- 3β -lower alkoxy- $1\alpha,2\beta,3\alpha,4,5\alpha,6\alpha$ -hexahydrobenzene- 1β -carboxylates, in which lower alkyl, containing from one to four carbon atoms, represents primarily methyl, as well as ethyl, n-propyl and the like, and lower alkoxy, containing from one to four carbon atoms, stands particularly for methoxy, as well as ethoxy, n-propoxy and the like, whereby the lower

alkoxy group is preferably attached to the 5-position or the 6-position of the indole portion of the molecule, or salts thereof. This group of intermediates may be represented by the lower alkyl $\Delta^4(21)$ -dehydro-3-lower alkoxy-18-O-lower alkyl-3-oxo-2,3;3,4-bis-seco-reserpates, particularly by the methyl $\Delta^4(21)$ -dehydro-3-methyl-18-O-methyl-3-oxo-2,3;3,4-bis-seco-reserpate, as well as analogous compounds, and acid addition salts thereof.

Another group of important intermediates is represented by the compounds of the formula:

in which each of the radicals R_1' , R_1'' and R_3 represents lower alkyl, containing preferably from one to four carbon atoms, particularly methyl, as well as ethyl, n-propyl and the like, or salts thereof.

A further group of important intermediates are the 18-etherified hydroxy-3,17-bis-lower alkoxy-3-oxo-2,3;3,4-bis-seco-allo-yohimbane 16-carboxylic acid esters, particularly the compounds of the formula:

in which R_1 , R_1'' , R_2 , R_3 , R_4 , R_5 and R_6 have the previously given meaning, or salts thereof. Each of the radicals R_1 , R_1'' and R_3 represents primarily lower alkyl, containing from one to four carbon atoms, particularly methyl, as well as ethyl and the like. These compounds may be represented by the compounds of the formula:

in which the radicals R_1' and R_1'' have the same meaning and stand for lower alkyl, containing preferably from one to four carbon atoms, particularly methyl, as well as ethyl and the like, R_3' represents lower alkyl, containing preferably from one to four carbon atoms, particularly methyl, as well as ethyl and the like, and R_4' represents lower alkoxy, containing preferably from one to four carbon atoms, especially methoxy as well as ethoxy and the like, or salts thereof. This group of intermediates is represented by the lower alkyl-3-lower alkoxy-18-O-lower alkyl-3-oxo-2,3;3,4-bis-seco-reserpates, particularly by methyl 3-methoxy-18-O-methyl-3-oxo-2,3;3,4-bis-seco-reserpate, or salts thereof.

Another group of important intermediates is represented by the compounds of the formula:

in which each of the radicals R_1' , R_1'' and R_3 represents lower alkyl, containing preferably from one to four carbon atoms, particularly methyl, as well as ethyl, n-propyl and the like, or salts thereof.

A further method for the preparation of the compounds of this invention comprises isomerizing 18-etherified hydroxy-17-lower alkoxy-allo-yohimbane 16-carboxylic acid esters, particularly compounds of the formula:

in which R_1 , R_2 , R_3 , R_4 , R_5 and R_6 have the above-given meaning, salts, N-oxides or salts of N-oxides thereof, by treatment with an acid and isolating the desired 18-etherified hydroxy-17-lower alkoxy-3-epi-allo-yohimbane 16-carboxylic acid esters, particularly the desired compounds of the formula:

in which R_1 , R_2 , R_3 , R_4 , R_5 and R_6 have the above-given meaning, salts, N-oxides or salts of N-oxides thereof, and, if desired, carrying out the optional steps.

Acids used in the above isomerization procedure are, for example, organic carboxylic acids, particularly aliphatic hydrocarbon carboxylic acids, such as lower alkanoic acids, e.g. acetic, propionic acid and the like, primarily glacial acetic acid, organic sulfonic acids, particularly carbocyclic aryl sulfonic acids, e.g. p-toluene sulfonic acid and the like, or lower alkane sulfonic acids, e.g. methane sulfonic acid and the like, or strong mineral acids such as hydrohalic acids, e.g. hydrogen chloride and the like, or mixtures of acids. For example, carbocyclic aryl sulfonic acids are advantageously used together with one of the aliphatic hydrocarbon carboxylic acids mentioned above, for example, p-toluene sulfonic acid

in glacial acetic acid. The reaction may be carried out in the absence or presence of an additional solvent; for example, p-tolene sulfonic acid may also be used in the presence of an organic base, e.g. collidine and the like, whereas hydrogen chloride may be used in an anhydrous lower alkanol, e.g. methanol, ethanol and the like. Isomerization may occur at room temperature or preferably at an elevated temperature, in an open vessel or under pressure, preferably in an atmosphere of nitrogen.

Optimum yields in the isomerization reaction may be obtained by removing the desired product from the reaction milieu, thus displacing the reaction equilibrium in favor of the product. The removal may be accomplished by separating the product, if desired, in the form of a salt thereof, from the starting material by exploiting the different relative solubilities in different solvent systems. For example, the product or a salt thereof may be separated from the starting material or a salt thereof either by adsorption on a suitable material, such as alumina, paper and the like, and subsequent fractional elution, or by fractional crystallization from a solvent or a mixture of solvents. The starting material separated from the desired product may then be recycled into the isomerization process, to enhance the overall yield of the reaction.

The starting materials used in the above procedure are new and are intended to be included within the scope of the invention. The 18-etherified hydroxy-17-lower alkoxy-allo-yohimbane 16-carboxylic acid esters, such as those of the above-given formula, are particularly illustrated by the compounds of the formula:

in which each of the radicals R_1' and R_3' represents lower alkyl, containing preferably from one to four carbon atoms, especially methyl, as well as ethyl, n-propyl, isopropyl and the like, and the radical R_4' stands for lower alkoxy, containing preferably from one to four carbon atoms, especially for methoxy, as well as ethoxy, n-propoxy and the like, whereby R_4' is preferably attached to the 10-position or the 11-position, acid addition salts, N-oxides or acid addition salts of N-oxides thereof. This group of compounds is represented by lower alkyl 18-O-lower alkyl-3-iso-reserpates, e.g. methyl 18-O-methyl-3-iso-reserpate, methyl 18-O-ethyl-3-iso-reserpate, methyl 18-O-n-propyl-3-iso-reserpate, ethyl 18-O-methyl-3-iso-reserpate, ethyl 18-O-ethyl-3-iso-reserpate, n-propyl 18-O-methyl-3-iso-reserpate, and the like, as well as by lower alkyl 18-O-lower alkyl-10-methoxy-3-iso-deserpates, e.g. methyl 10-methoxy-18-O-methyl-3-iso-deserpate, methyl 18-O-ethyl-10-methoxy-3-iso-deserpate, ethyl 10-methoxy-18-O-methyl-3-iso-deserpate and the like, or the acid addition salts thereof. Other compounds of the above-given type are the lower alkyl 18-O-lower alkyl-9-methoxy-3-iso-deserpates, e.g. methyl 9-methoxy-18-O-methyl-3-iso-deserpate, methyl 18-O-ethyl-9-methoxy-deserpate, ethyl 9-methoxy-18-O-methyl-3-iso-deserpate and the like, lower alkyl 11-ethoxy-18-O-lower alkyl-3-iso-deserpates, e.g. methyl 11-ethoxy-18-O-methyl-3-iso-deserpate, ethyl 11-ethoxy-18-O-n-propyl-3-iso-deserpate and the like, lower alkyl 18-O-lower alkyl-12-methoxy-3-iso-deserpate, e.g. methyl 12-methoxy-18-O-methyl-3-iso-deserpate, methyl 18-O-ethyl-12-

methoxy-3-iso-deserpate and the like, or acid addition salts of such and analogous compounds.

Another group of important starting materials useful in the above isomerization procedure are the lower alkyl 18-O-lower alkyl-3-iso-deserpates, e.g. methyl 18-O-methyl-3-iso-deserpate, methyl 18-O-ethyl-3-iso-deserpate, methyl 18-O-n-propyl-3-iso-deserpate, ethyl 18-O-methyl-3-iso-deserpate, ethyl 18-O-ethyl-3-iso-deserpate and the like, or salts of such compounds.

The 18-etherified hydroxy-17-lower alkoxy-allo-yohimbane 16-carboxylic acid esters used as the starting materials in the isomerization procedure may be prepared, for example, by removing in 18-etherified hydroxy-17-lower alkoxy-allo-yohimbane 16-carboxylic acid esters, in which a double bond extends from the 3-position to the 14-position, or salts thereof, in which a double bond extends from the 3-position to the 4-position, particularly in compounds of the formula:

in which R_1 , R_2 , R_3 , R_4 , R_5 and R_6 have the previously given meaning, in which a double bond extends from the 3-position to the 14-position, or salts thereof, in which a double bond extends from the 3-position to the 4-position, the double bond extending from the 3-position to either the 4-position or the 14-position, and, if desired, converting a resulting salt into the free compound, and, if desired, converting a resulting compound into a salt, an N-oxide or a salt of an N-oxide thereof.

The above-mentioned removal may be carried out by catalytic hydrogenation, for example, by treatment with hydrogen in the presence of a catalyst containing a metal of the eighth group of the Periodic System, e.g. nickel and the like, such as Raney nickel and the like, preferably in the presence of a solvent, such as a lower alkanol, e.g. methanol, ethanol and the like, or any other suitable diluent. The reduction may be carried out at normal or under an increased pressure, and/or under cooling, at room temperature or at an elevated temperature. The removal of the double bond may also be accomplished by treatment with a light metal hydride, particularly a borohydride, such as an alkali metal borohydride, e.g. lithium borohydride, sodium borohydride, potassium borohydride and the like, an alkaline earth metal borohydride, e.g. calcium borohydride, barium borohydride, strontium borohydride and the like, or an alkali metal lower alkoxy-borohydride, e.g. sodium trimethoxy-borohydride and the like. These reagents are preferably used in the presence of a solvent, such as, for example, a lower alkanol, e.g. methanol, ethanol and the like, or a formamide, e.g. formamide, N,N-dimethylformamide and the like or any other suitable diluent. The temperature may, if necessary, be elevated, and the reaction may be carried out under the atmosphere of an inert gas, e.g. nitrogen. The reduction of the double bond extending from the 3-position may also be carried out by treatment with a metal amalgam in the presence of a moist solvent, such as an alkali metal amalgam, e.g. sodium amalgam and the like, or aluminum amalgam in the presence of moist ether or any other suitable moist solvent.

The starting materials used in the isomerization procedure may also be produced, for example, by etherifying in 18-hydroxy-17-lower alkoxy-allo-yohimbane 16-car-

boxylic acid esters, particularly in compounds of the formula:

in which R_1 , R_2 , R_3 , R_4 , R_5 and R_6 have the above-given meaning, a salt, an N -oxide or a salt of an N -oxide thereof, the free hydroxyl group attached to the 18-position, and, if desired, carrying out the optional steps.

The above etherification of the secondary hydroxyl group attached to the 18-position may be carried out as previously shown, for example, by treatment with a diazo-reagent, such as an aliphatic diazo-hydrocarbon, such as a lower diazo-alkane, particularly diazomethane, as well as diazoethane, diazo-n-propane and the like, or a substituted aliphatic diazo-hydrocarbon, such as, for example, an etherified hydroxy-lower diazo-alkane and the like, in the presence of a strong Lewis acid, such as fluoroboric acid and the like.

The compounds of this invention may also be prepared, for example, by replacing in an 18-reactive esterified hydroxy-17-lower alkoxy-3-epi-allo-yohimbane 16-carboxylic acid ester, particularly in a compound of the formula:

in which R_1 , R_2 , R_4 , R_5 and R_6 have the previously given meaning, and E represents a reactive esterified hydroxyl group, a salt, an N -oxide or a salt of an N -oxide thereof, the reactive esterified hydroxyl group attached to the 18-position by an etherified hydroxyl group, and, if desired, carrying out the optional steps.

The hydroxyl group attached to the 18-position, which is reactively esterified, and is represented, for example, by the group E in the above formula, is preferably esterified by an organic sulfonic acid, such as an aliphatic hydrocarbon sulfonic acid, particularly lower alkane sulfonic acid, especially methane sulfonic acid and the like, or a monocyclic carbocyclic aryl sulfonic acid, especially p-nitro-benzene sulfonic acid and the like. The reactively esterified hydroxyl group, particularly the group E in the above formula, may, therefore, be represented by methane sulfonyloxy, p-nitro-benzene sulfonyloxy or analogous reactive esterified hydroxyl groups.

Replacement of the esterified hydroxyl group by an esterified hydroxyl group may be carried out by solvolysis, for example, by treatment with an alcohol of the formula R_3-OH , in which R_3 has the previously given meaning. Solvolysis reagents are, therefore, aliphatic hydroxy-hydrocarbon compounds, such as lower alkanols, particularly methanol, as well as ethanol, n-propanol, isopropanol, n-butanol and the like, or substituted aliphatic hydroxy-hydrocarbon, such as etherified hydroxy-lower alkanols and the like. The reaction may be carried out in the presence of a diluent, such as an excess amount of the solvolysis reagent, particularly a lower alkanol, such as methanol and the like, or another solvent, for example,

N,N -dimethylformamide, acetonitrile or an analogous solvent, such as a tertiary base and the like. Preferably, solvolysis occurs at an elevated temperature, for example, under reflux, if necessary, under increased pressure or in the atmosphere of an inert gas, e.g. nitrogen.

The replacement of the above-described reactive esterified hydroxyl group by an etherified hydroxyl group, may also occur by treatment with a metal compound of an alcohol of the formula R_3-OH , in which R_3 has the previously given meaning. Particularly useful as reagents are the alkali metal, e.g. lithium, sodium, potassium and the like, compounds of aliphatic hydroxy-hydrocarbons, such as lower alkanols, especially methanol, as well as ethanol, n-propanol and the like, or of substituted aliphatic hydroxy-hydrocarbons. The treatment of the starting materials with these metal reagents is preferably carried out in the presence of a solvent, such as, for example, N,N -dimethyl-formamide, acetonitrile and the like, if desired, in the presence of the alcohol forming the metal compound, such as a lower alkanol, particularly methanol, as well as ethanol and the like, and, if necessary, at an elevated temperature, under increased pressure and/or in the atmosphere of an inert gas, e.g. nitrogen and the like.

The starting materials used in the above procedure may be prepared according to methods used for the manufacture of analogous compounds. For example, the free hydroxyl group in an 18-hydroxy-17-lower alkoxy-3-epi-allo-yohimbane 16-carboxylic acid ester may be esterified by treatment of the mono-ester with a reactive derivative of an acid, particularly a halide, e.g. chloride and the like, thereof, in the presence of a tertiary base, e.g. pyridine and the like.

An additional procedure for the preparation of the compounds of this invention, particularly of 18-methoxy-17-lower alkoxy-3-epi-allo-yohimbane 16-esterified carboxylic acid esters, such as those of the formula:

in which R_1 , R_2 , R_4 , R_5 and R_6 have the previously given meaning, salts, N -oxides or salts of N -oxides, comprises converting in an 18-etherified hydroxy-17-lower alkoxy-3-epi-allo-yohimbane 16-carboxylic acid ester, in which the etherified hydroxyl group is capable of being converted into another etherified hydroxyl group, particularly in an 18-substituted methyl-17-lower alkoxy-3-epi-allo-yohimbane 16-carboxylic acid ester, such as in a compound of the formula:

in which R_1 , R_2 , R_4 , R_5 and R_6 have the previously given meaning, and the grouping $R_3''-O-$ represents an etherified hydroxyl group capable of being converted into another etherified hydroxyl group, particularly into a meth-

oxy group, or a salt thereof, the etherified hydroxyl group into another etherified hydroxyl, particularly into a methoxy group, and, if desired, carrying out the optional steps.

In the above starting materials, the etherified hydroxyl group attached to the 18-position is primarily represented by a methoxy group, which contains as a substituent a functional group capable of being replaced by a hydrogen atom. Such functional groups are, for example, etherified mercapto, such as lower alkylmercapto, e.g. methylmercapto, ethylmercapto and the like, carboxyl, halogeno, e.g. chloro, bromo and the like, or any other group, which can be replaced by hydrogen.

The above substituents are replaced by hydrogen according to methods, the selection of which depends primarily on the nature of the different functional groups representing these substituents. For example, etherified mercapto groups may be removed by treatment with a hydrogenation catalyst, containing preferably a metal of the eighth group of the periodic system, e.g. nickel and the like, such as Raney nickel or analogous hydrogenation catalysts. Or, a halogen atom may be replaced by hydrogen, for example, by treating the starting material with catalytically activated hydrogen, for example, hydrogen in the presence of a palladium-containing catalyst, or any other suitable hydrogenation procedure. A carboxyl group may be removed by decarboxylation, preferably at an elevated temperature. Other substituents may be replaced by hydrogen while using appropriate methods.

The starting materials used in the above procedure may be prepared, for example, by removing in 18-etherified hydroxyl-17-lower alkoxy-3-epi-allo-yohimbane 16-carboxylic acid ester salts, in which the etherified hydroxyl group is capable of being converted into another etherified hydroxyl group, and in which the nitrogen atom representing the 4-position carries a substituent capable of being removed, the substituent attached to the nitrogen atom of the 4-position. The removal of the latter may be carried out according to previously shown methods. The removal of the substituent attached to the 4-position to form the starting materials may occur simultaneously with the conversion of the etherified hydroxyl group of the 18-position into another etherified hydroxyl group, and the desired formation of the desired final products.

The above-described intermediates used for the preparation of the starting materials may be obtained, for example, by etherifying in an 18-hydroxy-17-lower alkoxy-3-epi-allo-yohimbane 16-carboxylic acid ester salt, which carries a removable substituent attached to the 4-position, the free hydroxyl group in the 18-position into an etherified hydroxyl group, which in the process of the invention is then capable of undergoing the transformation into the desired etherified hydroxyl group. This etherification may be performed according to previously described methods.

The compounds of the present invention, as well as the starting materials and intermediates used in their formation, may be present in the form of mixtures of racemates, single racemates or antipodes. Racemates of intermediates and final products may be resolved into antipodes. Racemates of final products or intermediates, which form acid addition salts, may be resolved, for example, by treating a solution of the free racemic base in a solvent, such as, for example, a lower alkanol, e.g. methanol, ethanol and the like, a halogenated lower aliphatic hydrocarbon, e.g. methylenechloride, chloroform and the like, or any other suitable solvent, with one of the optically active forms of an acid containing an asymmetric carbon atoms, which may be employed in solution, for example, in one of the above-mentioned solvents. A salt may then be isolated, which is formed by the optically active acid with one of the optically active forms of the base. Especially useful as optically active forms of salt-forming acids having an asymmetric carbon atom are D- and L-tartaric acid, as well as the optically active forms of di-o-

toluyl-tartaric, malic, mandelic, camphor-10-sulfonic, quinic acid and the like.

Compounds, containing functional groups forming salts with bases, may be resolved by reacting the free acid with the optically active form of a base containing an asymmetric carbon atom and thus forming a salt of such base with one of the optically active forms of the acid compound. Suitable, optically active bases are, for example, the optically active forms of brucine, strychnine, quinine, cinchonine, cinchonidine and the like.

Compounds, which contain neither acid, nor basic salt-forming functional groups, but have hydroxyl groups as substituents, may be converted into half-esters with dicarboxylic acids, for example, tetrahydrophthalic acid and the like; the resulting acidic compounds may then be resolved as shown hereinabove and the resulting, optically active half-ester may be hydrolyzed to the desired optically active compounds.

The optically active forms may also be obtained by resolution with biochemical methods.

From a resulting salt, the free and optically active compounds may be obtained according to known methods used for the conversion of a salt into a free compound, for example, as outlined hereinbelow; a resulting optically active base may be converted into an acid addition salt with one of the acids mentioned hereinbefore.

The compounds of this invention or the N-oxides thereof may be obtained in the form of the free bases or as the salts thereof. A salt including the salt of an N-oxide, may be converted into the free base, for example, by reacting the former with an alkaline reagent, such as, for example, aqueous ammonia and the like. A free base or the free N-oxide thereof may be converted into its therapeutically useful acid addition salts with one of the inorganic or organic acids outlined hereinbefore; the reaction may be carried out, for example, by treating a solution of the free base in a suitable solvent, such as a lower alkanol, e.g. methanol, ethanol, propanol, isopropanol and the like, a halogenated aliphatic hydrocarbon, e.g. methylene chloride, chloroform and the like, with the acid or a solution thereof and isolating the resulting salt. The salts may also be obtained as the hemihydrates, monohydrates, sesquihydrates or polyhydrates depending on the conditions used in the formation of the salts.

N-oxides of the compounds of the present invention may be formed according to known methods; for example, a resulting compound, preferably a solution thereof in an inert solvent, may be reacted with an N-oxidizing reagent, such as, for example, hydrogen peroxide, ozone, persulfuric acid, or more especially, organic peracids, such as organic percarboxylic acids, e.g. peracetic, perbenzoic, monoperphthalic acid and the like, or persulfonic acids, e.g. p-toluene persulfonic acid and the like. Inert solvents are, for example, halogenated lower alkanes, e.g. methylene chloride, chloroform, ethylene chloride and the like, lower alkanols, e.g. methanol, ethanol and the like, or any other suitable solvent. In the N-oxidation reaction an excess of the oxidation reagent and/or an increase in temperature should be avoided in order to prevent oxidative degradation.

The invention also comprises any modification of the process wherein a compound obtainable as an intermediate at any stage of the process is used as starting material and the remaining step(s) of the process is(are) carried out. It also includes any new intermediates, which may be formed in one of the procedures outlined hereinbefore.

In the process of this invention such starting materials are preferably used which lead to final products mentioned in the beginning as preferred embodiments of the invention.

The present application is a continuation-in-part application of our application Serial No. 837,357, filed September 1, 1959, now abandoned, which in turn is a continua-

tion-in-part application of our application Serial No. 830,187, filed July 29, 1959, now abandoned.

The following examples illustrate the invention and are not to be construed as being limitations thereon. Temperatures are given in degrees centigrade.

Example 1

To a solution of 2.48 g. of methyl reserpate in 400 ml. of methylene chloride, maintained at -10 to -15° , is added 66 ml. of a fluoboric acid solution while stirring. (The latter is prepared as follows: Commercially available fifty percent aqueous fluoboric acid is concentrated by partial evaporation under reduced pressure to an approximately 14 N solution, determined by titration with a standard sodium hydroxide solution. A stock solution of approximately 0.1 N strength is prepared by dissolving 1 ml. of the concentrated fluoboric acid in a mixture of 110 ml. of absolute ether and 30 ml. of methylene chloride.) A small precipitate forms during the addition, which represents, probably, a salt of methyl reserpate with the acid.

A solution of diazomethane in methylene chloride (69 ml. of a 0.348 N solution) is added to the stirred reaction mixture over a period of about five minutes, whereby the temperature is maintained at -10° . The previously mentioned precipitate dissolves again. An additional 1 ml. of the stock solution of fluoboric acid is given to the reaction mixture, and the solution is stirred for a few more minutes. 2 ml. of glacial acetic acid is added with the intent to destroy any excess of diazomethane.

The solution is washed twice with five percent aqueous sodium carbonate and once with saturated aqueous sodium chloride, the organic layer is dried over anhydrous sodium sulfate and evaporated under reduced pressure, whereupon 2.24 g. of a tan, solid material can be recovered. The product may be purified as follows: As much as possible of the residue is dissolved in 50-60 ml. of benzene at room temperature; the undissolved material is filtered off. The filtrate is chromatographed on about 40 g. of aluminum oxide (Woelm, neutral, activity I); the desired methyl 18-O-methyl-reserpate is eluted with benzene, containing 0.2 percent of methanol. The oily, yellow solid is washed with cold ether and recrystallized from a 1:3-mixture of benzene and cyclohexane, using charcoal as a decolorizing agent, M.P. 228-231 $^{\circ}$ (with decomposition).

The purification step may also be carried out as follows: 7.5 g. of benzene-soluble material, obtained from the tan, solid product, is dissolved in 100 ml. of benzene and placed on a column containing 240 g. of aluminum oxide (Woelm, neutral, activity II-III). The column is washed with about 500 ml. of benzene, and subsequently with about 3,000 ml. of methylene chloride and about 2,000 ml. of methylene chloride containing 0.5 percent of methanol. The fractions obtained with methylene chloride and the first fractions eluted with the methylene chloride-methanol mixture are combined after evaporation of the solvent and the residue is recrystallized using a 1:3-mixture of benzene and cyclohexane and charcoal as an adsorbent. The resulting, pure methyl 18-O-methyl-reserpate melts at 235-237 $^{\circ}$, $[\alpha]_D^{25} = -111$ (in chloroform), and is identical with the above-described product.

Example 2

Substitution of the diazomethane solution in Example 1 by 113 ml. of a 0.212 N solution of diazoethane, adding said solution to the mixture of 2.48 g. of methyl reserpate and 66 ml. of the standard fluoboric acid solution (as described in Example 1) in methylene chloride over a period of ten minutes and working up the reaction mixture as shown in Example 1, results in the formation of methyl 18-O-ethyl-reserpate which, after recrystallization from a 1:3-mixture of benzene and cyclohexane in the presence of charcoal, melts at 221-222.5 $^{\circ}$ (with decomposition).

Example 3

To a solution of 2.67 g. of n-propyl-reserpate and 66 ml. of a fluoboric acid solution (as described in Example 1) in methylene chloride is added 69 ml. of a 0.348 N solution of diazomethane in methylene chloride at below -10° . The reaction mixture is worked up as shown in Example 1 to yield the desired n-propyl 18-O-methyl-reserpate.

The starting material may be prepared as follows: 10 Gaseous n-diazopropane is distilled from its ether solution into a suspension of 20 g. of reserpic acid in a 1:1-mixture of chloroform and ethanol. Any excess of n-diazopropane is decomposed with acetic acid, the solvents are evaporated under reduced pressure and the residue is poured into 800 ml. of water containing 20 ml. of concentrated aqueous ammonia. A white crystalline precipitate is obtained, which is washed with water to yield the n-propyl reserpate, M.P. 164-166 $^{\circ}$.

Example 4

By replacing in Example 1 the methyl reserpate by 2.56 g. of ethyl reserpate and treating a mixture of the latter and a fluoboric acid preparation in methylene chloride with a diazomethane solution as shown in Example 1, the desired ethyl 18-O-methyl-reserpate can be obtained.

Example 5

Treatment of a solution of 2.67 g. of isopropyl reserpate and 66 ml. of the standard fluoboric acid preparation in methylene chloride with a diazomethane solution in methylene chloride at below -10° according to the procedure of Example 1, results in the formation of isopropyl 18-O-methyl-reserpate.

The starting material used in the above reaction may be prepared as follows: A mixture of 10 g. of methyl reserpate, 500 ml. of isopropanol and 20 drops of benzyl trimethyl ammonium hydroxide is refluxed for 2½ hours. After standing at room temperature for several hours, a white precipitate (needles) is formed, which is removed by filtration. The filtrate is evaporated to dryness, the foamy residue is taken up in 500 ml. of water containing 5 ml. of concentrated aqueous ammonia. The aqueous mixture is extracted with methylene chloride, the organic solvent is passed through a column containing a diatomaceous earth preparation and is then evaporated to dryness under reduced pressure. The residue is crystallized by the addition of diethyl ether, the crystalline material is filtered off, dried and identified as isopropyl reserpate, M.P. 214-216 $^{\circ}$.

Other lower alkyl 18-O-methyl-reserpates, which may be prepared according to the aforementioned procedures are, for example, n-butyl 18-O-methyl-reserpate, isobutyl 18-O-methyl-reserpate, isopentyl 18-O-methyl-reserpate, n-hexyl 18-O-methyl-reserpate and the like. The starting materials used for the preparation of the above compounds are known or may be obtained according to methods used for the known compounds, particularly by treatment of reserpic acid with lower diazo-alkanes; isobutyl reserpate melts at 145-148 $^{\circ}$ and isopentyl reserpate at 135-138 $^{\circ}$, whereas n-hexyl reserpate has a melting point of 117-118 $^{\circ}$.

Example 6

To a solution of 1.5 g. of methyl 18-O-methyl-reserpate in 25 ml. of acetone is added dropwise concentrated hydrochloric acid while stirring. The addition is carried out at room temperature and is interrupted after the solution becomes acidic to Congo Red test paper. Crystallization occurs upon scratching, the crystalline material is filtered off and washed with cold acetone. 1.5 g. of the methyl 18-O-methyl-reserpate hydrochloride is obtained, M.P. 237-242 $^{\circ}$ (with decomposition).

Example 7

75 To a methylene chloride solution of 1.15 g. of methyl

deserpide and 35 ml. of the standard fluoboric acid preparation described in Example 1 is added 35 ml. of a 0.348 N methylene chloride solution of diazomethane at a temperature of below -10° . The reaction mixture is worked up as shown in Example 1 and yields the methyl 18-O-methyl-deserpide.

Methyl deserpide may be replaced by other lower alkyl deserpides in the above example, and compounds, such as ethyl 18-O-methyl-deserpide, n-propyl 18-O-methyl-deserpide, methyl 18-O-ethyl-deserpide, methyl 18-O-n-butyl-deserpide and the like, are formed upon treatment of the corresponding lower alkyl deserpides with lower diazo-alkanes according to the procedure of Example 1.

Example 8

By reacting a solution of 0.92 g. of 2-methoxyethyl reserpate and 22 ml. of the standard fluoboric acid preparation in methylene chloride with diazomethane as shown in Example 1, the desired 2-methoxyethyl 18-O-methyl-reserpate can be formed.

The starting material may be prepared as follows: To a mixture of 226 g. of a 33 percent aqueous solution of 2-methoxyethylamine and 150 ml. of diethyl ether, kept at 5° to 10° in an ice bath, is added dropwise 54 g. of ethyl chloroformate. 100 g. of a cold 40% aqueous solution of sodium hydroxide and a second portion of 54 g. of ethyl chloroformate are given to the mixture, which is stirred for one hour. The ether layer is separated, the aqueous phase is extracted with 100 ml. of diethyl ether, and the two ether solutions are combined and dried over potassium carbonate. The solvent is evaporated under reduced pressure and the ethyl N-(2-methoxyethyl)-carbamate is distilled at 105 – 106° /17–20 mm.

To a solution of 33 g. of ethyl N-(2-methoxyethyl)-carbamate in 200 ml. of diethyl ether are added 25 g. of cracked ice and a solution of 81 g. of sodium nitrite in 125 ml. of water. While keeping the temperature below 15° , 150 g. of 35% aqueous nitric acid is added carefully over a period of one hour. The ether layer is separated, washed with water and aqueous potassium carbonate and then dried over potassium carbonate. The residue, obtained after evaporation of the solvent under reduced pressure, represents the ethyl N-(2-methoxyethyl)-N-nitroso-carbamate, which is used without further purification.

A gently refluxing solution of 5 g. of potassium hydroxide in 15 g. of methanol and 150 ml. of diethyl ether is treated with a solution of 15.5 g. of ethyl N-(2-methoxyethyl)-N-nitroso-carbamate in 50 ml. of diethylether, which is added dropwise over a period of one hour. After refluxing for 5 minutes, 100 ml. of water is added and the yellow ether solution, containing the 2-methoxy-diazoethane, is separated.

The above ether solution of 2-methoxy-diazoethane is reacted with small portions of a slurry of reserpic acid in methanol until no further reaction can be observed. A few drops of acetic acid are added, the solution is evaporated under reduced pressure and the residual oil is dissolved in ethyl acetate. Upon addition of petroleum ether a precipitate is formed, which is filtered off, dissolved in methylene chloride, which solution is washed with aqueous ammonia and filtered through a small column containing a diatomaceous earth. The residue, obtained after evaporation of the solvent, is crystallized from ethyl acetate to yield the 2-methoxyethyl reserpate, M.P. 183–185°.

Other compounds which may be prepared according to the previously given procedure by replacing the starting material by other intermediates are, for example, 2-ethoxyethyl 18-O-methyl-reserpate, 2-n-propyloxyethyl 18-O-methyl-reserpate, 2-isopropyloxyethyl 18-O-methyl-reserpate, 3-methoxypropyl 18-O-methyl-reserpate, 2-methoxyethyl 18-O-ethyl-reserpate, 2-methoxyethyl 18-O-n-propyl-reserpate, 2-methoxyethyl 18-O-methyl-deser-

5 pide, 2-methoxyethyl 18-O-ethyl-deserpide and the like.

Example 9

To a solution of 4.55 g. of methyl reserpate in 730 ml. of methylene chloride is given 121 ml. of the concentrated fluoboric acid solution described in Example 1. 150 ml. of a 0.3 molar solution of n-diazobutane is added and the reaction mixture is treated and worked up as shown in Example 1. The resulting methyl 18-O-n-butyl-reserpate is recrystallized from a mixture of benzene and cyclohexane, M.P. 219–221° (with decomposition).

Example 10

15 A solution of 0.5 g. of 18-O-methyl-reserpic acid in a mixture of methanol and methylene chloride is given to an ether solution of diazoethane. The reaction mixture is allowed to stand, an excess of diazoethane is destroyed by adding benzoic acid, the solvent is evaporated, a small amount of ammonia is added and the organic material is extracted with methylene chloride. The resulting residue is crystallized from a mixture of benzene and cyclohexane to yield the desired ethyl 18-O-methyl-reserpate.

20 The starting material may be prepared by heating a solution of 1 g. of methyl 18-O-methyl-reserpate in aqueous ethanol containing 0.5 g. of sodium hydroxide, evaporating the solvent and converting the residue into the 18-O-methyl-reserpic acid hydrochloride by treatment with hydrogen chloride. The free base is liberated from the salt by treatment with ammonia.

25 The starting material may also be prepared, for example, by reacting benzyl reserpate (obtained from reserpic acid lactone with benzyl alcohol in the presence of the sodium compound of benzyl alcohol) with diazomethane in the presence of fluoboric acid as described in Example 1 and converting the resulting benzyl 18-O-methyl-reserpate into the desired starting material by treatment with hydrogen in the presence of a catalytic amount of palladium on charcoal.

30 Other 18-O-lower alkyl-reserpic acids used as intermediates, such as, for example, 18-O-ethyl-reserpic acid, 18-O-n-propyl-reserpic acid and the like, may be prepared as shown hereinbefore. The above procedure may also be used for the manufacture of other intermediates, such as 18-O-lower alkyl-10-methoxy-deserpide acids, e.g. 10-methoxy-18-O-methyl-deserpide acid, 18-O-ethyl-10-methoxy-deserpide acid and the like, or 18-O-lower alkyl-deserpide acids, e.g. 18-O-methyl-deserpide acid, 18-O-ethyl-deserpide acid and the like, as well as other analogous acids, such as, for example, 5-methyl-18-O-methyl-reserpic acid, 5-methyl-18-O-methyl-deserpide acid, 6-methyl-18-O-methyl-reserpic acid, 9-methyl-18-O-methyl-deserpide acid, 11-methyl-18-O-methyl-deserpide acid, 9-methoxy-18-O-methyl-deserpide acid, 10-methoxy-18-O-methyl-reserpic acid, 12-methoxy-18-O-methyl-deserpide acid, 11-ethoxy-18-O-methyl-deserpide acid, 18-O-methyl-11-n-propyloxy-deserpide acid, 11-isopropyloxy-18-O-methyl-deserpide acid, 11-n-butyloxy-18-O-methyl-deserpide acid, 18-O-methyl-10,11-methylenedioxy-deserpide acid, 10-benzyloxy-18-O-methyl-deserpide acid, 11-benzyloxy-18-O-methyl-deserpide acid, 18-O-methyl-11-methylmercapto-deserpide acid, 11-ethylmercapto-18-O-methyl-deserpide acid, 10-chloro-18-O-methyl-deserpide acid, 10-bromo-18-O-methyl-deserpide acid, 17-desmethoxy-17-ethoxy-18-O-methyl-reserpic acid, 17-desmethoxy-18-O-methyl-17-n-propyloxy-reserpic acid, 17-desmethoxy-17-isopropyloxy-18-O-methyl-reserpic acid and the like. The above intermediates may be used for the preparation of the compounds of this invention by esterification of the free carboxyl group, for example, by treatment with a lower diazo-alkane, particularly diazomethane, as well as diazoethane, n-diazopropane and the like, as shown hereinbefore.

Example 11

A solution of 1.25 g. of methyl 10-methoxy-deserpidate and about 35 ml. of the fluoboric acid preparation described in Example 1 in methylene chloride, when treated with a diazomethane solution in methylene chloride at a temperature below -10° according to the method outlined in Example 1, yields the desired methyl 10-methoxy-18-O-methyl-deserpidate.

Upon treatment with hydrochloric acid according to the method described in Example 6, the methyl 10-methoxy-18-O-methyl-deserpidate hydrochloride is formed.

Other lower alkyl 18-O-lower alkyl-10-methoxy-deserpidates, such as, for example, methyl 18-O-ethyl-10-methoxy-deserpidate, methyl 10-methoxy-18-O-n-propyl-deserpidate, n-propyl 10-methoxy-18-O-methyl-deserpidate and the like, are prepared by treating appropriate lower alkyl 10-methoxy-deserpidates with the desired lower diazoalkanes according to the method described in detail in Example 1.

Other 18-etherified hydroxy-17-lower alkoxy-3-epi-allo-yohimbane 16-carboxylic acid esters, which may be prepared according to the method of Example 1 by selecting the appropriate starting materials, are, for example, lower alkyl 18-O-lower alkyl-5-methyl-reserpates, e.g. methyl 5-methyl-18-O-methyl-reserpate, methyl 18-O-ethyl-5-methyl-reserpate, ethyl 5-methyl-18-O-methyl-reserpate and the like, lower alkyl 18-O-lower alkyl-5-methyl-deserpidates, e.g. methyl 5-methyl-18-O-methyl-deserpidate, methyl 5-methyl-18-O-n-propyl-deserpidate, ethyl 5-methyl-18-O-methyl-deserpidate and the like, lower alkyl 18-O-lower alkyl-6-methyl-reserpates, e.g. methyl 6-methyl-18-O-methyl-reserpate, methyl 18-O-ethyl-6-methyl-reserpate, n-propyl 6-methyl-18-O-methyl-reserpate and the like, lower alkyl 18-O-lower alkyl-9-methyl-deserpidates, e.g. methyl 9-methyl-18-O-methyl-deserpidate, methyl 18-O-n-butyl-9-methyl-deserpidate, ethyl 9-methyl-18-O-methyl-deserpidate and the like, lower alkyl 18-O-lower alkyl-11-methyl-deserpidates, e.g. methyl 11-methyl-18-O-methyl-deserpidate, methyl 11-methyl-18-O-n-propyl-deserpidate, n-propyl 11-methyl-18-O-methyl-deserpidate and the like, lower alkyl 18-O-lower alkyl-9-methoxy-deserpidates, e.g. methyl 9-methoxy-18-O-methyl-deserpidate, methyl 18-O-ethyl-9-methoxy-deserpidate, ethyl 9-methoxy-18-O-methyl-deserpidate and the like, lower alkoxy 18-O-lower alkyl-10-methoxy-reserpates, e.g. methyl 10-methoxy-18-O-methyl-reserpate, methyl 18-O-ethyl-10-methoxy-reserpate, ethyl 10-methoxy-18-O-methyl-reserpate and the like, lower alkyl 18-O-lower alkyl-12-methoxy-deserpidates, e.g. methyl 12-methoxy-18-O-methyl-deserpidate, methyl 18-O-n-butyl-12-methoxy-deserpidate, n-propyl 12-methoxy-18-O-methyl-deserpidate and the like, lower alkyl 11-ethoxy-18-O-lower alkyl-deserpidates, e.g. methyl 11-ethoxy-18-O-methyl-deserpidate, methyl 11-ethoxy-18-O-ethyl-deserpidate, ethyl 11-ethoxy-18-O-methyl-deserpidate and the like, lower alkyl 18-O-lower alkyl-11-n-propyloxy-deserpidates, e.g. methyl 18-O-methyl-11-n-propyloxy-deserpidate, methyl 18-O-n-propyl-11-n-propyloxy-deserpidate, ethyl 18-O-methyl-11-n-propyloxy-deserpidate and the like, lower alkyl 11-isopropyloxy-18-O-lower alkyl-deserpidates, e.g. methyl 11-isopropyloxy-18-O-methyl-deserpidate, methyl 18-O-ethyl-11-isopropyloxy-deserpidate, n-butyl 11-isopropyloxy-18-O-methyl-deserpidate and the like, lower alkyl 11-n-butyloxy-18-O-lower alkyl-deserpidates, e.g. methyl 11-n-butyloxy-18-O-methyl-deserpidate, methyl 11-n-butyloxy-18-O-ethyl-deserpidate, ethyl 11-n-butyloxy-18-O-methyl-deserpidate and the like, lower alkyl 18-O-lower alkyl 10, 11-methylenedioxy-deserpidates, e.g. methyl 18-O-methyl-10, 11-methylenedioxy-deserpidate, methyl 18-O-ethyl-10, 11-methylenedioxy-deserpidate, ethyl 18-O-methyl-10, 11-methylenedioxy-deserpidate and the like, lower alkyl 10-benzyloxy-18-O-lower alkyl-deserpidates, e.g. methyl

10-benzyloxy-18-O-methyl-deserpidate, methyl 10-benzyloxy-18-O-ethyl-deserpidate, n-propyl 10-benzyloxy-18-O-methyl-deserpidate and the like, lower alkyl 11-benzyloxy-18-O-lower alkyl-deserpidates, e.g. methyl 11-benzyloxy-18-O-methyl-deserpidate, methyl 11-benzyloxy-18-O-ethyl-deserpidate, ethyl 11-benzyloxy-18-O-methyl-deserpidate and the like, lower alkyl 18-O-lower alkyl-11-methylmercapto-deserpidates, e.g. methyl 18-O-methyl-11-methylmercapto-deserpidate, methyl 18-O-ethyl-11-methylmercapto-deserpidate, n-propyl 18-O-methyl-11-methylmercapto-deserpidate and the like, lower alkyl 11-ethylmercapto-18-O-lower alkyl-deserpidates, e.g. methyl 11-ethylmercapto-18-O-methyl-deserpidate, methyl 11-ethylmercapto-18-O-n-propyl-deserpidate, ethyl 11-ethylmercapto-18-O-methyl-deserpidate and the like, lower alkyl 10-chloro-18-O-lower alkyl-deserpidates, e.g. methyl 10-chloro-18-O-methyl-deserpidate, methyl 10-chloro-18-O-n-propyl-deserpidate, isopropyl 10-chloro-18-O-methyl-deserpidate and the like, lower alkyl 10-bromo-18-O-lower alkyl-reserpates, e.g. methyl 10-bromo-18-O-methyl-reserpate, methyl 10-bromo-18-O-n-butyl-reserpate, ethyl 10-bromo-18-O-methyl-reserpate and the like, lower alkyl 17-desmethoxy-17-ethoxy-18-O-lower alkyl-reserpates, e.g. methyl 17-desmethoxy-17-ethoxy-18-O-methyl-reserpate, methyl 17-desmethoxy-17-ethoxy-18-O-n-propyl-reserpate, n-propyl 17-desmethoxy-17-ethoxy-18-O-methyl-reserpate and the like, lower alkyl 17-desmethoxy-18-O-lower alkyl 17-n-propyloxy-reserpates, e.g. methyl 17-desmethoxy-18-O-methyl-reserpate, methyl 17-n-propyloxy-reserpate, ethyl 17-desmethoxy-18-O-methyl-17-n-propyloxy-reserpate and the like, lower alkyl 17-desmethoxy-17-isopropyloxy-18-O-lower alkyl-reserpates, e.g. methyl 17-desmethoxy-17-isopropyloxy-18-O-methyl-reserpate, methyl 17-desmethoxy-18-O-ethyl-17-isopropyloxy-reserpate, ethyl 17-desmethoxy-18-O-ethyl-17-isopropyloxy-reserpate and the like, lower alkyl 17-desmethoxy-17-ethoxy-18-O-lower alkyl-deserpidates, e.g. methyl 17-desmethoxy-17-ethoxy-18-O-methyl-deserpidate, methyl 17-desmethoxy-17-ethoxy-18-O-isobutyl-deserpidate, ethyl 17-desmethoxy-17-ethoxy-18-O-methyl-deserpidate and the like.

Example 12

45 A solution of 0.5 g. of methyl 18-O-methyl-reserpate, prepared, for example, according to the procedure of Example 1, when refluxed in ethanol in the presence of benzyl trimethyl ammonium hydroxide over a short period of time, yields the desired ethyl 18-O-methyl-reserpate, identical with the product obtained according to the procedure of Example 4.

Example 13

55 To a solution of 0.75 g. of methyl Δ^3 -dehydro-18-O-methyl-reserpate, in which the double bond probably extends from the 3-position to the 14-position, in a mixture of 8 ml. of tetrahydrofuran, 8 ml. of acetone and 7.2 ml. of water are added 0.8 ml. of concentrated perchloric acid of about 70 percent strength and then 0.7 g. of powdered zinc. The mixture is refluxed while constantly stirring for fifteen minutes under an atmosphere of nitrogen, and then evaporated to dryness under reduced pressure. The oily residue is dissolved in 20 ml. of a 3:2-mixture of acetone and water, the solution is made basic with aqueous ammonia and the organic solvent is evaporated off. 25 ml. of water is added, the organic material is extracted with methylene chloride and the organic solution is dried over sodium sulfate and then evaporated to dryness to leave 0.72 g. of a foamy material.

The residue is chromatographed on 20 g. of alumina (Woelm, neutral, activity II to III). The following fractions are collected and each of the fractions subjected to paper chromatography in the system chloroform/

formamide to determine the identity of the various fractions:

Fraction	Solvent	Amount, g.	Rf-value
1.....	50 ml. of benzene.....	0.200	0.15 (trace). 0.83 (trace). 0.90.
2.....	do.....	0.025	0.15 (trace). 0.83.
3.....	50 ml. of methylene chloride.....	0.160	0.15 (trace). 0.83.
4.....	do.....	0.080	0.83.
5.....	do.....	0.050	0.83.
6.....	do.....	0.010	0.83.
7.....	150 ml. of methylene chloride, containing 0.5 percent of methanol.	0.160	0.83.
8.....	100 ml. of methanol.....	0.030	0.00 and impurities.

Fractions 2 to 7 inclusive are combined and dissolved in a hot 1:3-mixture of benzene and cyclohexane, and the solution is concentrated until crystalline material is formed. A first crop of 0.35 g. representing methyl 18-O-methyl-reserpate melts at 230-233° and has a rotation of $[\alpha]_D^{25} = -108^\circ$. The infrared absorption curve is identical with the one of methyl 18-O-methyl-reserpate prepared according to the procedure described in Example 1. The ultraviolet absorption spectrum in ethanol (values given in $m\mu$) shows the following maxima: 226-228 ($\epsilon = 34350$), 264—shoulder ($\epsilon = 4710$), 274-272 ($\epsilon = 4960$) and 296-299 ($\epsilon = 6200$), and minima: 252 ($\epsilon = 3620$) and 281-282 ($\epsilon = 4120$).

The starting material may be prepared by treating methyl 3-oxo-2,3-seco-reserpate with diazomethane in the presence of a fluoroboric acid preparation described in Example 1 and treating the resulting methyl 18-O-methyl-3-oxo-2,3-seco-reserpate with phosphorus oxychloride. A mixture of the resulting salt in dilute acetic acid is made basic with aqueous ammonia, the yellow precipitate is extracted with methylene chloride, the organic solution is dried over sodium sulfate and evaporated to dryness to yield the desired methyl Δ^3 -dehydro-18-O-methyl-reserpate, in which the double bond probably extends from the 3-position to the 14-position, as a foam, which is directly used in the above reaction. A small amount is recrystallized from ethyl acetate, M.P. 201-205°; it has a rotation of $[\alpha]_D^{25} + 122 \pm 10$, and shows the following ultraviolet absorption spectrum (values in $m\mu$) in ethanol: maxima at 221—shoulder ($\epsilon = 20520$), 227-232—plateau ($\epsilon = 18770$), 255-256 ($\epsilon = 9220$), 264-265 ($\epsilon = 9020$), 290-295 ($\epsilon = 8990$), 317-319 ($\epsilon = 17100$), 330-331 ($\epsilon = 16980$) and 390 ($\epsilon = 4720$), and minima at 252 ($\epsilon = 9130$), 260-262 ($\epsilon = 8960$), 273-278 ($\epsilon = 7490$), 294-295 ($\epsilon = 8900$) 324-325 ($\epsilon = 15780$) and 348 ($\epsilon = 3800$); and in ethanol, containing a small amount of hydrochloric acid: maxima at 239 ($\epsilon = 4920$), 258-260 ($\epsilon = 6200$), 297-302—plateau ($\epsilon = 1170$) and 386-388 ($\epsilon = 25480$), and minima at 231-232 ($\epsilon = 4860$), 242-246 ($\epsilon = 4500$) and 280-282 ($\epsilon = 60$).

The methyl Δ^3 -dehydro-18-O-methyl-reserpate perchlorate, in which the double bond extends from the 3-position to the 4-position may be prepared as follows: To a solution of 0.035 g. of the previously described methyl Δ^3 -dehydro-18-O-methyl-reserpate in 10 ml. of a 1:1-mixture of methanol and water are added several drops of aqueous perchloric acid of 35 percent strength. The solid material is filtered off and recrystallized from ethanol to yield the methyl Δ^3 -dehydro-18-O-methyl-reserpate perchlorate, M.P. 149-154°. This salt may be used in the above reduction procedure to form the desired methyl 18-O-methyl-reserpate.

The methyl 18-O-methyl-3-oxo-2,3-seco-reserpate used as the intermediate in the preparation of the starting material may also be obtained, for example, by esterifying in methyl 3 β -hydroxy-2 α -methoxy-7-oxo-1 α ,2 β ,3 α ,4,7,8,9 α -,10 α -octahydro-naphthalene 1 β -carboxylate the free hydroxyl group with diazomethane in the presence of fluoroboric acid. The resulting methyl 2 α ,3 β -dimethoxy-7-oxo-

1 α ,2 β ,3 α ,4,7,8,9 α ,10 α -octahydro-naphthalene 1 β -carboxylate is then oxidized first with osmium tetroxide to the methyl 5 α ,6 α -dihydroxy-2 α ,3 β -dimethoxy-7-oxo-1 α ,2 β ,3 α ,4,5 β ,6 β ,7,8,9 α ,10 α -decahydro-naphthalene 1 β -carboxylate and then with periodic acid hydrate to the methyl 5 β -aldehydo-6 β -carboxymethyl-2 α ,3 β -dimethoxy-1 α ,2 β ,3 α ,4,5 α ,6 α -hexahydro-benzene 1 β -carboxylate, which is then esterified with diazomethane to the methyl 5 β -aldehydo-6 β -carboxymethoxy-methyl-2 α ,3 β -dimethoxy-1 α ,2 β ,3 α ,4,5 α ,6 α -hexahydro-benzene 1 β -carboxylate. The latter is then condensed with 6-methoxy-tryptamine in benzene to form the methyl $\Delta^4(21)$ -dehydro-3-methoxy-18-O-methyl-3-oxo-2,3;3,4-bis-seco-reserpate, which in turn is treated with sodium borohydride to reduce the Schiff-base type double bond. After re-esterification of hydrolyzed carboxyl groups the resulting methyl 3-methoxy-18-O-methyl-3-oxo-2,3;3,4-bis-seco-reserpate is treated with acetic acid anhydride in pyridine to yield the desired methyl 18-O-methyl-3-oxo-2,3-seco-reserpate used as the intermediate in the preparation of the starting material.

Other lower alkyl Δ^3 -dehydro-18-O-lower alkyl-reserpates are, for example, methyl Δ^3 -dehydro-18-O-ethyl-reserpate, methyl Δ^3 -dehydro-18-O-n-propyl-reserpate, methyl Δ^3 -dehydro-18-O-n-butyl-reserpate, ethyl Δ^3 -dehydro-18-O-methyl-reserpate, ethyl Δ^3 -dehydro-18-O-n-propyl-reserpate, n-propyl Δ^3 -dehydro-18-O-ethyl-reserpate, isopropyl Δ^3 -dehydro-18-O-methyl-reserpate, n-butyl Δ^3 -dehydro-18-O-methyl-reserpate, isobutyl Δ^3 -dehydro-18-O-methyl-reserpate and the like, in which the double bond probably extends from the 3-position to the 14-position, and salts of these compounds, such as the perchlorate and the like, in which the double bond extends from the 3-position to the 4-position.

Other highly useful intermediates are the lower alkyl Δ^3 -dehydro-18-O-lower alkyl-10-methoxy-deserpipates, e.g. methyl Δ^3 -dehydro-10-methoxy-18-O-methyl-deserpipate, methyl Δ^3 -dehydro-18-O-ethyl-10-methoxy-deserpipate, methyl Δ^3 -dehydro-10-methoxy-18-O-n-propyl-deserpipate, ethyl Δ^3 -dehydro-10-methoxy-18-O-methyl, n-propyl Δ^3 -dehydro-10-methoxy-18-O-methyl-deserpipate and the like, or lower alkyl Δ^3 -dehydro-18-O-lower alkyl deserpipates, e.g. methyl Δ^3 -dehydro-18-O-methyl-deserpipate, methyl Δ^3 -dehydro-18-O-ethyl-deserpipate, ethyl Δ^3 -dehydro-18-O-methyl-deserpipate, n-propyl Δ^3 -dehydro-18-O-methyl-deserpipate and the like, in which compounds the double bond probably extends from the 3-position to the 14-position, or salts thereof, such as the perchlorate and the like, in which the double bond extends from the 3-position to the 4-position, as well as lower alkyl Δ^3 -dehydro-18-O-lower alkyl-5-methyl-reserpates, e.g. methyl Δ^3 -dehydro-5-methyl-18-O-methyl-reserpate and the like, lower alkyl Δ^3 -dehydro-18-O-lower alkyl-6-methyl-reserpates, e.g. methyl Δ^3 -dehydro-6-methyl-18-O-methyl-reserpate and the like, lower alkyl Δ^3 -dehydro-18-O-lower alkyl-6-methyl-deserpipates, e.g. methyl Δ^3 -dehydro-6-methyl-18-O-methyl-deserpipate and the like, lower alkyl Δ^3 -dehydro-9-methyl-18-O-methyl-deserpipate and the like, lower alkyl Δ^3 -dehydro-11-methyl-18-O-methyl-deserpipate and the like, lower alkyl Δ^3 -dehydro-18-O-lower alkyl-9-methoxy-deserpipates, e.g. methyl Δ^3 -dehydro-9-methoxy-18-O-methyl-deserpipate and the like, lower alkyl Δ^3 -dehydro-18-O-lower alkyl-10-methoxy-reserpates, e.g. methyl Δ^3 -dehydro-10-methoxy-18-O-methyl-reserpate and the like, lower alkyl Δ^3 -dehydro-11-ethoxy-18-O-lower alkyl-deserpipates, e.g. methyl Δ^3 -dehydro-11-ethoxy-18-O-methyl-deserpipate and the like, lower alkyl Δ^3 -dehydro-18-O-lower alkyl-11-n-propyloxy-deserpipates, e.g. methyl Δ^3 -dehydro-18-O-methyl-11-n-propyloxy-deserpipate and the like, lower alkyl Δ^3 -dehydro-11-isopropyloxy-18-O-lower alkyl-deserpipates, e.g. methyl Δ^3 -dehydro-11-isopropyloxy-18-O-methyl-deserpipate and the like, lower alkyl Δ^3 -dehydro-

11-n-butyloxy-18-O-lower alkyl-deserpидates, e.g. methyl Δ^3 - dehydro-11-n-butyloxy-18-O-methyl-deserpидate and the like, lower alkyl Δ^3 -dehydro-18-O-lower alkyl-12-methoxy-deserpидates, e.g. methyl Δ^3 -dehydro-12-methoxy-18-O-methyl-deserpидate and the like, lower alkyl Δ^3 -dehydro-18-O-lower alkyl-10,11-methylenedioxy-deserpидates, e.g. methyl Δ^3 -dehydro-18-O-methyl-10,11-methylenedioxy-deserpидate and the like, lower alkyl Δ^3 -dehydro-18-O-lower alkyl-11-methylmercapto-deserpидates, e.g. methyl Δ^3 - dehydro-18-O-methyl-11-methylmercapto-deserpидate and the like, lower alkyl Δ^3 -dehydro-11-ethylmercapto-18-O-lower alkyl-deserpидates, e.g. methyl Δ^3 -dehydro-11-ethyl-mercapto-18-O-methyl-deserpидate and the like, lower alkyl Δ^3 -dehydro-10-chloro-18-O-lower alkyl-deserpидates, e.g. methyl Δ^3 -dehydro-10-chloro-18-O-methyl-deserpидate and the like, lower alkyl Δ^3 -dehydro-10-bromo-18-O-lower alkyl-reserpates, e.g. methyl Δ^3 -dehydro-10-bromo-18-O-methyl-reserpate and the like, lower alkyl Δ^3 -dehydro-17-desmethoxy-17-ethoxy-18-O-lower alkyl-reserpates, e.g. methyl Δ^3 -dehydro-17-desmethoxy-17-ethoxy-18-O-methyl-reserpate and the like, lower alkyl Δ^3 -dehydro-17-n-propyloxy-reserpates, e.g. methyl Δ^3 -dehydro-17-desmethoxy-18-O-methyl-17-n-propyloxy-reserpate and the like, lower alkyl Δ^3 -dehydro-17-desmethoxy-17-ethoxy-18-O-lower alkyl-deserpидates, e.g. methyl Δ^3 -dehydro-17-desmethoxy-17-ethoxy-18-O-methyl-deserpидate and the like, or analogous compounds, in which the double bond probably extends from the 3-position to the 14-position, and salts of these compounds, in which the double bond extends from the 3-position to the 4-position. Upon reduction of the double bond extending from the 3-position, these compounds can be converted into the desired compounds of this invention.

Important intermediates used for the preparation of these starting materials are the lower alkyl 18-O-lower alkyl-3-oxo-2,3-seco-reserpates, such as the above-mentioned methyl 18-O-methyl-3-oxo-2,3-seco-reserpate, as well as the methyl 18-O-ethyl-3-oxo-2,3-seco-reserpate, methyl 18-O-n-propyl-3-oxo-2,3-seco-reserpate, ethyl 18-O-methyl-3-oxo-2,3-seco-reserpate, n-propyl 18-O-methyl-3-oxo-2,3-seco-reserpate and the like, lower alkyl 18-O-lower alkyl-10-methoxy-3-oxo-2,3-seco-deserpидates, e.g. methyl 10-methoxy-18-O-methyl-3-oxo-2,3-seco-deserpидate, methyl 18-O-ethyl-10-methoxy-3-oxo-2,3-seco-deserpидate, ethyl 10-methoxy-18-O-methyl-3-oxo-2,3-seco-deserpидate, n-propyl 10-methoxy-18-O-methyl-3-oxo-2,3-seco-deserpидate and the like, or lower alkyl 18-O-lower alkyl-3-oxo-2,3-seco-deserpидates, e.g. methyl 18-O-methyl-3-oxo-2,3-seco-deserpидate, methyl 18-O-ethyl-3-oxo-2,3-seco-deserpидate, ethyl 18-O-methyl-3-oxo-2,3-seco-deserpидate, n-propyl 18-O-methyl-3-oxo-2,3-seco-deserpидate and the like, as well as lower alkyl 18-O-lower alkyl-5-methyl-3-oxo-2,3-seco-reserpates, e.g. methyl 5-methyl-18-O-methyl-3-oxo-2,3-seco-reserpate and the like, lower alkyl 18-O-lower alkyl-6-methyl-3-oxo-2,3-seco-reserpates, e.g. methyl 6-methyl-18-O-methyl-3-oxo-2,3-seco-reserpate and the like, lower alkyl 18-O-lower alkyl-6-methyl-3-oxo-2,3-seco-deserpидates, e.g. methyl 6-methyl-18-O-methyl-3-oxo-2,3-seco-deserpидate and the like, lower alkyl 18-O-lower alkyl-9-methyl-3-oxo-2,3-seco-deserpидates, e.g. methyl 9-methyl-18-O-methyl-3-oxo-2,3-seco-deserpидate and the like, lower alkyl 18-O-lower alkyl-11-methyl-3-oxo-2,3-seco-deserpидates, e.g. methyl 11-methyl-18-O-methyl-3-oxo-2,3-seco-deserpидate and the like, lower alkyl 18-O-lower alkyl-9-methoxy-3-oxo-2,3-seco-deserpидates, e.g. methyl 9-methoxy-18-O-methyl-3-oxo-2,3-seco-deserpидate and the like, lower alkyl 18-O-lower alkyl-10-methoxy-3-oxo-2,3-seco-reserpates, e.g. methyl 10-methoxy-18-O-methyl-3-oxo-2,3-seco-reserpate and the like, lower alkyl 11-ethoxy-18-O-lower alkyl-3-oxo-2,3-seco-deserpидates, e.g. methyl 11-ethoxy-18-O-methyl-3-oxo-2,3-seco-deserpидate and the like, lower alkyl 18-O-lower alkyl-11-n-propylxy-3-oxo-2,3-seco-deserpидates, e.g. methyl 18-O-methyl-11-n-propylxy-3-oxo-2,3-seco-

deserpdate and the like, lower alkyl 11-isopropoxy-18-O-lower alkyl-3-oxo-2,3-seco-deserpdates, e.g. methyl 11-isopropoxy-18-O-methyl-3-oxo-2,3-seco-deserpdate and the like, lower alkyl 11-n-butyloxy-18-O-lower alkyl-3-oxo-2,3-seco-deserpdates, e.g. methyl 11-n-butyloxy-18-O-methyl-3-oxo-2,3-seco-deserpdate and the like, lower alkyl 18-O-lower alkyl-12-methoxy-3-oxo-2,3-seco-deserpdates, e.g. methyl 12-methoxy-18-O-methyl-3-oxo-2,3-seco-deserpdate and the like, lower alkyl 18-O-lower alkyl-10,11-methylenedioxy-3-oxo-2,3-seco-deserpdates, e.g. methyl 8-O-methyl-10,11-methylenedioxy-3-oxo-2,3-seco-deserpdate and the like, lower alkyl 18-O-lower alkyl-11-methylmercapto-3-oxo-2,3-seco-deserpdates, e.g. methyl 18-O-methyl-11-methylmercapto-3-oxo-2,3-seco-deserpdate and the like, lower alkyl 11-ethylmercapto-18-O-lower alkyl-3-oxo-2,3-seco-deserpdates, e.g. methyl 11-ethylmercapto-18-O-methyl-3-oxo-2,3-seco-deserpdate and the like, lower alkyl 10-chloro-18-O-lower alkyl-3-oxo-2,3-seco-deserpdates, e.g. methyl 10-chloro-18-O-methyl-3-oxo-2,3-seco-deserpdate and the like, lower alkyl 10-bromo-18-O-lower alkyl-3-oxo-2,3-seco-reserpates, e.g. methyl 10-bromo-18-O-methyl-3-oxo-2,3-seco-reserpate and the like, lower alkyl 17-desmethoxy-17-ethoxy-18-O-lower alkyl-3-oxo-2,3-seco-reserpates, e.g. methyl 17-desmethoxy-17-ethoxy-18-O-methyl-3-oxo-2,3-seco-reserpate and the like, lower alkyl 17-desmethoxy-17-ethoxy-18-O-lower alkyl-3-oxo-2,3-seco-reserpates, e.g. methyl 17-desmethoxy-17-ethoxy-18-O-methoxy-3-oxo-2,3-seco-reserpates, e.g. methyl 17-desmethoxy-18-O-methyl-17-n-propyloxy-3-oxo-2,3-seco-reserpates and the like, lower alkyl 17-desmethoxy-17-ethoxy-18-O-lower alkyl-3-oxo-2,3-seco-deserpdates, e.g. methyl 17-desmethoxy-17-ethoxy-18-O-methoxy-3-oxo-2,3-seco-deserpdate and the like, or analogous lower alkyl 17,18-lower alkoxy-3-oxo-2,3-seco-allo-yohimbane 16-carboxylates. These compounds, upon ring closure, for example, with phosphorus oxychloride yield the desired lower alkyl Δ^3 -dehydro-17,18-lower alkoxy-allo-yohimbane 16-carboxylates or salts thereof, which are used as the starting materials in the previously described procedure.

Example 14

A solution of 1.0 g. of methyl 18-O-methyl-3-isoreserpate is heated in 35 ml. of glacial acetic acid for about twenty-four hours under an atmosphere of nitrogen. The reaction mixture is concentrated under reduced pressure to a small volume, water is added to the residue and the solution is extracted with chloroform. The organic solution is separated, washed with water and evaporated under reduced pressure. From the residue, the desired methyl 18-O-methyl-reserpate, which is identified by paper chromatography, can be isolated by chromatography on aluminum oxide; the resulting product is identical with the compound obtained according to the procedure of Example 1.

The starting material used in the above procedure may be prepared, for example, by treating an ethanol solution of methyl Δ^3 -dehydro-18-O-methyl-reserpate, if desired, in the form of a salt thereof, with sodium borohydride.

Further compounds, which may be used as starting materials in the above-described isomerization procedure are, apart from the methyl 18-O-methyl-3-iso-reserpate or salts thereof, other lower alkyl 18-O-lower alkyl-3-iso-reserpates, e.g. methyl 18-O-ethyl-3-iso-reserpate, methyl 18-O-n-propyl-3-iso-reserpate, methyl 18-O-isobutyl-3-iso-reserpate, ethyl 18-O-methyl-3-iso-reserpate and the like, 60 lower alkyl 18-O-lower alkyl-10-methoxy-3-iso-deserpidates, e.g. methyl 10-methoxy-18-O-methyl-3-iso-deserpidate, methyl 18-O-ethyl-10-methoxy-3-iso-deserpidate, methyl 10-methoxy-18-O-n-propyl-3-iso-deserpidate, ethyl 10-methoxy-18-O-methyl-3-iso-deserpidate, and the like, 65 or lower alkyl 18-O-lower alkyl-3-iso-deserpidates, e.g. methyl 18-O-methyl-3-iso-deserpidate, methyl 18-O-ethyl-3-iso-deserpidate, methyl 18-O-n-propyl-3-iso-deserpidate, ethyl 18-O-methyl-3-iso-deserpidate, n-propyl 18-O-methyl-3-iso-deserpidate and the like, or salts of these compounds as well as other lower alkyl 17,18-lower alkoxy- 70 75

allo-yohimbane 16-carboxylates, which contain substituents, such as those previously mentioned, attached to the available portions. These compounds are useful as starting materials in the isomerization procedure described in the example hereinbefore.

The starting material used in the above procedure may also be prepared, for example, by etherifying in methyl 3-iso-reserpate, or any other lower alkyl 18-hydroxy-lower alkoxy-allo-yohimbane 16-carboxylate, the free hydroxyl group in the 18-position by treatment with diazomethane, or another lower diazoalkane, in the presence of fluoboric acid.

Example 15

To a solution of 2.48 g. of methyl reserpate in 120 ml. of methylene chloride, kept at room temperature, is added 1 ml. of chloromethyl methyl ether. The reaction mixture is concentrated to dryness under reduced pressure and the residue, containing the quaternary salt of methyl reserpate with chloromethyl methyl ether, is dried for one hour under reduced pressure on the steam bath.

The above residue is dissolved in 400 ml. of methylene chloride and 270 ml. of a solution of 1 ml. of 14 N fluoboric acid in 110 ml. of dry diethyl ether and 30 ml. of methylene chloride is added. The solution is chilled to -10° and stirred while 150 ml. of 0.326M diazomethane in methylene chloride is added over a period of about five minutes. After standing for fifteen minutes, the solution is washed with 5 percent aqueous sodium carbonate and then with a saturated aqueous solution of sodium chloride. The organic layer is dried over sodium sulfate and concentrated to dryness under reduced pressure to yield 1.06 g. of a residue, containing the desired quaternary salt of methyl 18-O-methyl-reserpate with chloromethyl methyl ether.

The residue is dissolved in a solution of 15 ml. of methanol in 50 ml. of water, the solution is made acid to a pH of about 3 with concentrated hydrochloric acid and allowed to stand at room temperature for $1\frac{1}{4}$ hours. It is then made basic with ammonia and extracted with methylene chloride; the organic layer is separated, dried and concentrated to dryness, and the residue is extracted with 50 ml. of benzene. The benzene solution is evaporated to yield 1 g. of solid material. The desired methyl 18-O-methyl-reserpate is identified paper-chromatographically by comparing it with the product obtained according to the procedure of Example 1.

The methyl 18-O-methyl-reserpate can also be obtained by reacting methyl reserpate with benzyl bromide in a mixture of N,N-dimethylformamide and methylene chloride, etherifying in the resulting quaternary salt of methyl reserpate with benzyl bromide the free hydroxyl group by treating a solution of the salt in methylene chloride with a diazomethane solution in the presence of the standard fluoboric acid solution and reacting a methanol solution of the quaternary salt formed by methyl 18-O-methyl-reserpate and benzyl bromide with hydrogen in the presence of a palladium catalyst (ten percent of palladium on charcoal), at room temperature and under atmospheric pressure. The identity of the desired methyl 18-O-methyl-reserpate can be determined by comparison with the product obtained according to the procedure of Example 1, for example, by paper chromatography.

Example 16

A solution of 3.31 g. of methyl reserpate N-oxide benzoate in methylene chloride is treated at about -10° with 150 ml. of 0.326M of diazomethane in methylene chloride in the presence of 270 ml. of the solution of fluoboric acid described in Example 1. The reaction is carried out as shown in the previous example; the methylene chloride solution is concentrated to give 1.5 g. of a solid material containing the desired salt of methyl 18-O-methyl-reserpate N-oxide salt.

The residue is dissolved in 85 ml. of glacial acetic acid, 8.5 g. of zinc dust is added, and the mixture is heated

on the steam bath for fifteen minutes, then filtered and cooled. The filtrate is poured into 150 ml. of cold water, the mixture is extracted with methylene chloride, and the aqueous portion is made basic with a twenty percent solution of sodium carbonate. The aqueous portion is extracted with methylene chloride, the organic layer is separated, dried and evaporated to dryness. The residue is extracted with benzene, the benzene solution is concentrated to dryness to yield a residue, which contains the desired methyl 18-O-methyl-reserpate. The compound is identified by paper chromatography and found identical with the methyl 18-O-methyl-reserpate obtained according to the procedure of Example 1.

Example 17

15 A solution of 0.43 g. of methyl 18-O-methyl-reserpate in 40 ml. of methylene chloride is cooled to 0° , and, while stirring, 3 ml. of 0.339M perbenzoic acid in chloroform is added over a period of seven minutes. The cold, pink solution is stirred for an additional fifteen minutes in an ice-bath, then extracted twice with a cold five percent aqueous sodium carbonate solution and washed with a saturated aqueous sodium chloride solution. The organic layer is separated, dried over sodium sulfate and evaporated to dryness under reduced pressure. The residue is dissolved in methylene chloride, and the solution is placed on a column of aluminum oxide (Woelm, neutral, activity II-III). The column is washed with methylene chloride and the product is eluted with methylene chloride containing one percent of methanol. The solvent is evaporated, and the residue is triturated with acetone to yield 0.11 g. of crystalline material, which is recrystallized by dissolving it in methylene chloride, adding acetone and evaporating most of the methylene chloride. The white, crystalline methyl 18-O-methyl-reserpate N-oxide melts at 238° with decomposition.

Example 18

The compounds of the present invention may be used in the form of pharmaceutically acceptable preparations. For example, methyl 18-O-methyl-reserpate may be used in therapeutically acceptable tablets containing 0.00025 g. of the active substance (procedure for 10,000 tablets):

Ingredients	G.
Methyl 18-O-methyl-reserpate	2.500
Lactone spray dried	942.500
Corn starch	50.000
Magnesium stearate U.S.P.	5.000

50 The methyl 18-O-methyl-reserpate is triturated with the corn starch and the mixture is forced through a No. 60 screen. The lactone and the magnesium stearate is passed through a No. 20 screen, and all ingredients are mixed in a suitable mixer until the mix is homogenous. Tablets weighing 0.1 g. are compressed using 0.25 inch punches and dies.

55 Tablets containing 0.0005 g. of methyl 18-O-methyl-reserpate are prepared as follows (procedure for 10,000 tablets):

Ingredients			
Methyl 18-O-methyl-reserpate	g.	5.000	
Lactose U.S.P.	g.	1420.000	
Tragacanth 550	g.	15.000	
Polyethylene glycol 6000	g.	30.000	
Talc U.S.P.	g.	22.500	
Magnesium stearate U.S.P.	g.	7.500	
3A alcohol 50%	q.s.		

60 The methyl 18-O-methyl-reserpate is triturated with the tragacanth and forced through a No. 60 screen. The lactose, the talc and the magnesium stearate are forced through a No. 20 screen, and all ingredients are mixed until homogenous. The polyethylene glycol is dissolved in 40 ml. of the alcohol, and the above-mixed powder is wetted with this solution, if necessary by adding an additional amount of alcohol. The moist mass is passed

through a No. 10 screen and dried at about 37°. The resulting granules are broken on a No. 16 screen. Tablets weighing 0.150 g. are compressed using $\frac{1}{2}$ inch dies and standard concave punches, uppers bisected. Instead of methyl 18-O-methyl-reserpate, other compounds of this invention, salts, N-oxides or salts of N-oxides of these compounds, such as, for example, the methyl 18-O-methyl-reserpate hydrochloride, may be used in therapeutically acceptable forms, such as tablets, solutions, elixirs and the like.

Example 19

A composition suitable for veterinary use, containing methyl 18-O-methyl-reserpate hydrochloride, may be prepared as follows:

Premix—

Methyl 18 - O-methyl-reserpate hydrochloride	G.
	22.00
Wheat standard middlings 30-80 mesh	10,978.00
Total weight	11,000.00

Feed formula—

Corn meal	1082.875
Fat	80.00
Fish meal 60% protein	100.00
Soybean meal 50% protein	500.00
Corn gluten meal	100.00
Dehydrated alfalfa meal	50.00
Corn distiller solubles	40.00
Di-calcium carbonate	28.00
Iodized salt	10.00
Vitamins A and D (1,000,000 A and 250,000 D/pound)	4.000
Calcium pantothenate	.250
Butylated hydroxy toluene	.250
Choline chloride 25%	2.500
Riboflavin conc. (24 g. per pound)	.125
Vitamin B ₁₂ (0.02 g. per pound)	1.000
Methionine	.500
Manganese sulphate	.500
Total weight	2000.000

The premix is made by adding the methyl 18-O-methyl-reserpate hydrochloride to the wheat and then mixing until uniformity is obtained.

The feed formula is prepared as follows: A portion of the corn meal is introduced into the blending machine (about half of the amount to be added). The remaining corn meal, previously blended with the pre-heated, liquified fat, is added thereto and mixing is continued until uniformity is obtained. The manganese sulphate, di-calcium carbonate and iodized salt are then added with mixing, followed by the addition of the fish meal, soy bean meal, corn gluten meal and corn distiller solubles. After a uniform mixture has been obtained, vitamins A and D, calcium pantothenate, choline chloride, riboflavin, vitamin B₁₂ and methionine are added in this order. Mixing is continued after the addition of butylated hydroxy toluene, and maintained until a uniform form product is obtained.

The premix is added to the feed formula prepared as described above in an amount sufficient to provide a concentration of 0.02 g. of methyl 18-O-methyl-reserpate hydrochloride per 1000 g. of feed in the uniformly blended mix.

For sedation and quieting of birds one may desirably use from about 0.005 g. to about 0.100 g., especially from about 0.020 g. to about 0.040 g. of methyl 18-O-methyl-reserpate hydrochloride per 1000 g. of feed.

Sedation in animals, particularly in poultry, may also be accomplished by adding, for example, the water-soluble methyl 18-O-methyl-reserpate hydrochloride to the drinking water; aqueous solutions of methyl 18-O-methyl-reserpate hydrochloride of about 0.0004 to about 0.01 percent, particularly of about 0.0015 to about 0.003 per-

cent, are adequate for quieting animals to facilitate handling, primarily at the time of vaccination, shipment and the like.

What is claimed is:

1. Lower alkyl 2 α -methoxy-7-oxo-3 β -lower alkoxy-1 α ,2 β ,3 α ,4,7,8,9 α ,10 α -octahydronaphthalene-1 β -carboxylate.
2. Methyl 2 α ,3 β - dimethoxy-7-oxo-1 α ,2 β ,3 α ,4,7,8,9 α ,10 α -octahydronaphthalene-1 β -carboxylate.
3. Lower alkyl 5 α ,6 α -dihydroxy-2 α -methoxy-7-oxo-3 β -lower alkoxy-1 α ,2 β ,3 α ,4,5 β ,6 β ,7,8,9 α ,10 α -decahydronaphthalene-1 β -carboxylate.

4. Methyl 5 α ,6 α -dihydroxy-2 α ,3 β -di-methoxy-7-oxo-1 α ,2 β ,3 α ,4,5 β ,6 β ,7,8,9 α ,10 α -decahydronaphthalene - 1 β -carboxylate.
5. Lower alkyl 5 β - aldehydo-6 β -carboxymethyl-2 α -methoxy - 3 β -lower alkoxy-1 α ,2 β ,3 α ,4,5 α ,6 α -hexahydrobenzene-1 β -carboxylate.

6. Methyl 5 β - aldehydo - 6 β -carboxymethyl-2 α ,3 β -di-methoxy - 1 α ,2 β ,3 α ,4,5 α ,6 α - hexahydrobenzene-1 β -carboxylate.
7. Lower alkyl 5 β -aldehydo-6 β -carbo-lower alkoxy-methyl - 2 α - methoxy-3 β -lower alkoxy-1 α ,2 β ,3 α ,4,5 α ,6 α -hexahydrobenzene-1 β -carboxylate.

8. Methyl 5 β -aldehydo-6 β -carbomethoxy-methyl-2 α ,3 β -dimethoxy - 1 α ,2 β ,3 α ,4,5 α ,6 α - hexahydrobenzene-1 β -carboxylate.
9. A member of the group consisting of α compound of the formula:

in which R₁ stands for a member of the group consisting of lower alkyl, lower alkoxy-lower alkyl, in which lower alkyl separates lower alkoxy from the carboxyl group by at least two carbon atoms, and N,N-di-lower alkyl-amino-lower alkyl, in which lower alkyl separates N,N-di-lower alkyl-amino from the carboxyl group by two to three carbon atoms, R₁'' is lower alkyl, R₄ stands for lower alkyl, R₅ is a member of the group consisting of lower alkyl, lower alkoxy-lower alkyl, in which lower alkyl separates lower alkoxy from the oxygen atom by two to three carbon atoms, and N,N-di-lower alkyl-amino-lower alkyl, in which lower alkyl separates N,N-di-lower alkyl-amino from the oxygen atom by two to three carbon atoms, each of the radicals R₄ and R₅ stands for a member of the group consisting of hydrogen, lower alkyl, lower alkoxy, phenyl lower alkoxy, lower alkyl-mercapto, halogeno, and, whenever attached to adjacent positions and taken together, lower alkylenedioxy, and R₆, attached to one of the positions selected from the group consisting of position 5 and position 6, stands for a member of the group consisting of hydrogen and lower alkyl, and an acid addition salt thereof.

10. A compound of the formula:

in which each of the radicals R_1' and R_1'' stands for lower alkyl, R_3' is lower alkyl, and R_4' stands for lower alkoxy.

11. Lower alkyl $\Delta^4(21)$ -dehydro-3-lower alkoxy-18-O-lower alkyl-3-oxo-2,3;3,4-bis-seco-reserpate.
  12. Methyl $\Delta^4(21)$ -dehydro-3-methoxy-18-O-methyl-3-oxo-2,3;3,4-bis-seco-reserpate.
  13. Lower alkyl $\Delta^4(21)$ -dehydro-3-lower alkoxy-18-O-lower alkyl-3-oxo-2,3;3,4-bis-seco-deserpitate.

14. A member of the group consisting of a compound 10 of the formula:

in which R_1 stands for a member of the group consisting of lower alkyl, lower alkoxy-lower alkyl, in which lower alkyl separates lower alkoxy from the carboxyl group by at least two carbon atoms, and N,N-di-lower-alkyl-amino-lower alkyl, in which lower alkyl separates N,N-di-lower alkyl-amino from the carboxyl group by two to three carbon atoms, R_1'' is lower alkyl, R_2 stands for lower alkyl, R_3 is a member of the group consisting of lower alkyl, lower alkoxy-lower alkyl, in which lower alkyl separates lower alkoxy from the oxygen atom by two to three carbon atoms, and N,N-di-lower alkyl amino-lower alkyl, in which lower alkyl separates N,N-di-lower alkyl-amino from the oxygen atom by two to three carbon

atoms, each of the radicals R_4 and R_5 stands for a member of the group consisting of hydrogen, lower alkyl, lower alkoxy, phenyl-lower alkoxy, lower alkyl-mercapto, halogeno, and, whenever attached to adjacent positions and taken together, lower alkyleneoxy, and R_6 , attached to one of the positions selected from the group consisting of position 5 and position 6, stands for a member of the group consisting of hydrogen and lower alkyl, and an acid addition salt thereof.

- 10 15. A compound of the formula:

in which each of the radicals R_1' and R_1'' stands for lower alkyl, R_3' is lower alkyl, and R_4' stands for lower alkoxy.

- 25 16. Lower alkyl 3-lower alkoxy-18-O-lower-alkyl-3-
oxo-2,3;3,4-bis-seco-reserpate.
17. Methyl 3 - methoxy-18-O-methyl-3-oxo-2,3;3,4-bis-
seco-reserpate.
18. Lower alkyl 3-lower alkoxy-18-O-lower alkyl-3-
30 oxo-2,3;3,4-bis-seco-deserpidate.

UNITED STATES PATENT OFFICE
CERTIFICATE OF CORRECTION

Patent No. 3,119,819

January 28, 1964

Michael Mullen Robison et al.

It is hereby certified that error appears in the above numbered patent requiring correction and that the said Letters Patent should read as corrected below.

Column 54, line 27, for "a" read -- a --; line 57, after "phenyl" insert a hyphen; column 55, line 34, for "alkyl amino-" read -- alkyl-amino- --.

Signed and sealed this 16th day of June 1964.
